AUTOMATIC SWITCH

Bernard D. Willis, Oak Park, Ill., assignor to Associated Electric Laboratories, Inc., Chicago, Ill., a corporation of Delaware

Original application February 7, 1941, Serial No. 377,835. Divided and this application August 23, 1941, Serial No. 408,053

9 Claims. (Cl. 179—27.52)

The present invention relates to automatic switches and more particularly to automatic switches of an improved type adapted for use in automatic telephone systems of the character of that disclosed in U. S. Patent No. 2,222,131, Bernard D. Willis, granted November 19, 1940. The present application is a division of the copending application of Bernard D. Willis, Serial No. 377,835, filed February 7, 1941.

In an automatic telephone system of the character of that disclosed in the Willis patent the subscriber-controlled switching apparatus provided for setting up connections between the various subscriber lines is so connected and arranged that it may be selectively controlled by a single impulse of variable length or time duration, as contrasted with conventional subscriber-controlled switching apparatus which is selectively controlled by a variable series of impulses of equal length or time duration.

While the telephone system disclosed in the Willis patent is thoroughly satisfactory in operation and entirely adequate to handle the traffic in a small exchange, such as a private automatic branch exchange, it is not of sufficiently flexible connection and arrangement to handle the traffic in a large exchange, such as a central automatic exchange.

Accordingly, it is an object of the present invention to provide an improved automatic telephone system of the character noted, which is so connected and arranged that it is sufficiently flexible to handle the traffic in any exchange, regardless of the size of the exchange.

Another object of the invention is to provide in an automatic telephone system, an improved selector capable of making both line group and individual line selections, which is selectively controllable by a single impulse of variable length or time duration.

Another object of the invention is to provide in an automatic telephone system, an improved connector capable of making both line group and individual line selections, which is selectively controllable by a plurality of single impulses of variable length or time duration.

A further object of the invention is to provide in an automatic switching system, an improved switching arrangement which is selectively operative upon a constant-speed-variable-time-interval basis.

A further object of the invention is to provide in an automatic switch of the type having primary and secondary movements, an improved arrangement for selectively controlling the pri-

mary movement of the switch in accordance with the time duration of a single impulse transmitted thereto and for selectively controlling the secondary movement of the switch automatically.

5 A further object of the invention is to provide in an automatic switch of the type having primary and secondary movements, an improved arrangement for selectively controlling both the primary and secondary movements of the switch 10 in accordance with the time durations of two successive single impulses of variable time duration transmitted thereto.

A still further object of the invention is to provide an improved mechanical switch which is of 15 simple and economical construction, and which is positive and reliable in operation.

In general, the objects set forth above are attained in accordance with the present invention by providing in a telephone system, a calling 20 line, a called line, a calling device selectively operative repeatedly to transmit a plurality of single impulses of variable time duration over the calling line, and means including a plurality of tandem related switches adapted to be selectively controlled sequentially in accordance with the time durations of the impulses for setting up 25 a connection between the calling line and the called line. More particularly, the switches are arranged in a switch train including a selector and a tandem related connector, the selector being so connected and arranged that it is responsive to a single impulse transmitted over the calling line to make a first selection in accordance with the time duration of a single impulse 30 and then automatically to make a second selection, and the connector being so connected and arranged that it is responsive to first and second impulses transmitted over the calling line to make first and second selections respectively 35 in accordance with the time durations of the first and second impulses.

In accordance with one feature of the invention, both the selector and the connector constitute an automatic switch of the type having primary and secondary movements. The selector embodies means responsive to the transmission of a single impulse over an associated circuit for selectively controlling the primary movement thereof in accordance with the time duration of the single impulse and automatic means for selectively controlling the secondary movement thereof, whereby the selector is first operated in its primary movement to select one of a plurality of groups of trunks accessible thereto, and is then operated automatically in its

secondary movement to select any idle one of the trunks from the previously selected group of trunks. The connector embodies means responsive to the transmission of first and second single impulses of variable time duration over an associated circuit for first selectively controlling the primary movement thereof in accordance with the time duration of the first impulse and then for selectively controlling the secondary movement thereof in accordance with the time duration of the second impulse, whereby the connector is operated in its primary movement to select one of a plurality of groups of lines accessible thereto and is then operated in its secondary movement to select any individual one of the lines from the previously selected group of lines. The selector embodies busy control apparatus operative in the event all of the trunks in the previously selected group of trunks are busy; while the connector embodies line testing apparatus operative to test the idle or busy condition of the lines selected thereby and then operative to return busy tone current over the associated connection or to project ringing current over the selected line, depending respectively upon the busy or idle condition of the selected line. Finally, both the selector and the connector embody release apparatus responsive both to the opening of the associated connection and to false dialing over the associated connection to effect the release thereof.

In accordance with another feature of the invention both the selector and the connector are selectively controlled sequentially in tandem over a calling subscriber line associated therewith by a unique calling device at the calling subscriber substation to which the calling line extends, this calling device being operative repeatedly to alter the condition of the calling line from a given condition and then to restore the calling line to the given condition after a predetermined variable time interval, or to transmit a single impulse of variable length or time duration over the calling line, wherein the time duration is directly controlled in accordance with the digit dialed on the calling device. More particularly, the time interval comprises one or more unit time intervals corresponding to the digit dialed on the calling device.

In accordance with a further feature of the invention both the selector and the connector embody a mechanical switch of unique construction and arrangement; which mechanical switch may be of either of two forms. A first form of the mechanical switch comprises a rectangular contact bank and an associated wiper capable of both lateral and longitudinal movements in the respective primary and secondary movements thereof; while the second form of the mechanical switch comprises a semi-cylindrical contact bank and an associated wiper capable of both rotary and longitudinal movements in the respective primary and secondary movements thereof. Each of the switches comprises shift mechanism for selectively controlling both the primary and the secondary movements thereof; and clutch mechanism for selectively controlling both the amount of primary movement and the amount of secondary movement of the switch. Also, each of the switches is operatively associated with a continuously rotating drive shaft which is rotated at a substantially constant speed and comprises drive control mechanism including a cylindrical spiral connection, whereby both the primary movement and the secondary movement of each switch is effected at a constant rate.

Thus, each movement of each switch is effected at a constant rate for a variable time interval, whereby each switch is operative upon a constant-speed-variable-time-interval basis.

- 5 Further features of the invention pertain to the particular arrangement of the mechanical elements of the switches, whereby the above-outlined and additional operating features are attained.
- 10 The novel features believed to be characteristic of the invention are set forth with particularity in the appended claims. The invention, both as to its organization and method of operation, together with further objects and advantages thereof, will best be understood by reference to the following specification taken in connection with the accompanying drawings, in which Figure 1 is a fragmentary plan view of one form of an automatic switch constructed and arranged in accordance with the present invention; Fig. 2 is a fragmentary and elevational view of the switch shown in Fig. 1; Fig. 3 is a fragmentary side elevational view of the switch shown in Figs. 1 and 2; Fig. 4 is a fragmentary plan view of a modified form of an automatic switch constructed and arranged in accordance with the present invention; Fig. 5 is a fragmentary side elevational view of the switch shown in Fig. 4; and Figs. 6 and 7, taken together, illustrate diagrammatically an automatic telephone system connected and arranged in accordance with the present invention.

Construction and operation of the first form of the automatic switch

35 Referring now more particularly to Figs. 1 to 3, inclusive, of the drawings, there is illustrated a first form of an automatic switch 100 embodying the present invention, which comprises a substantially U-shaped support 101 including a flat bottom wall 102 and two longitudinally spaced-apart upstanding end walls 103 and 104, and an operating shaft 105 suitably journaled in bearings provided in the end walls 103 and 104. 40 Also, the switch 100 comprises a longitudinally movable carriage 106 slidably supported upon two laterally spaced-apart guide rods 107 and 108 arranged in substantially parallel relation and extending longitudinally between the end walls 103 and 104 of the support 101. More particularly, two tubular bushings 109 and 110 respectively surround the guide rods 107 and 108 and are respectively fixed in openings provided in the opposite sides of the carriage 106, thereby to facilitate longitudinal sliding thereof upon the guide rods 107 and 108 between the end walls 103 and 104.

45 The operating shaft 105 comprises an enlarged cylindrical section 111 disposed intermediate the ends thereof, which enlarged section 111 has a longitudinally extending spiral or helical groove 112 cut in the outer surface thereof. Also, the enlarged section 111 of the operating shaft 105 carries a tubular member 113 on the outer surface thereof, a pin 114 being fixed to the tubular member 113 and projecting into the spiral groove 112 cut in the outer surface of the enlarged section 111, for a purpose more fully explained hereinafter. The tubular member 113 comprises a sprocket wheel 115, a ratchet wheel 116 and an annular flange 117, the sprocket wheel 115 and the ratchet wheel 116 being separated by an annular groove 118 formed in the surface of the tubular member 113 and the ratchet wheel 116 and the annular flange 117 being separated

by an annular groove 119 formed in the surface of the tubular member 113.

The upper central portion of the carriage 106 has a substantially semicircular recess 120 formed therein, thereby to provide upstanding side walls disposed in the annular groove 118 formed in the tubular member 113. Also, the carriage 106 comprises a laterally extending shelf 121 having a longitudinally extending slot 122 formed therein. Further, the carriage 106 carries two upstanding bifurcated lugs 123 and 124 on the opposite sides thereof which are respectively arranged in straddling relation with the guide rods 107 and 108. Two sprocket wheels 125 and 126 are rotatably mounted upon the guide rods 107 and 108, respectively, the sprocket wheel 125 being arranged between one end of the tubular bushing 109 and the lug 123, and the sprocket wheel 126 being arranged between one end of the tubular bushing 110 and the lug 124.

Further, the switch 100 comprises a laterally movable slide 127 carrying a contact controlling member 10A in the form of a wiper set. At this point it is noted that the control wiper of the wiper set 10A is of the bridging type; while the line wipers thereof are not of the bridging type, this arrangement being utilized for a purpose more fully explained hereinafter. The slide 127 comprises two side pieces 129 and 130 between which the individual wipers of the wiper set 10A are clamped, by two screws 131, the individual wipers of the wiper set 10A being insulated from each other and from the slide 127 by interposed strips of insulation 132. Also, the slide 127 comprises a substantially T-shaped carrying piece 133 arranged in the slot 122 formed in the shelf 121 of the carriage 106, the stem of the carrying piece 133 being securely clamped to the wiper set 10A by the screws 131.

The head of the carrying piece 133 is securely clamped to an endless chain 134, comprising a plurality of individual links flexibly connected together, by an arrangement including a plate 135 and two screws 136. The endless chain 134 is arranged in meshing relation with the sprocket wheel 115, which constitutes a driving sprocket wheel, and the two sprocket wheels 125 and 126, which constitute idler sprocket wheels. Further, the slide 127 carries two guide members 137 arranged in spaced-apart relation which are utilized for a purpose more fully explained hereinafter. Also, the side pieces 129 and 130 of the slide 127 are respectively provided with guiding projections 128 and 139 adjacent the upper ends thereof which cooperate with the slot 122 provided in the shelf 121 of the carriage 106 in order positively to guide the lateral movement of the slide 127 with respect to the carriage 106. Finally, the side pieces 129 and 130 of the slide 127 respectively carry contact control projections 140 and 141 adjacent the lower ends thereof, for a purpose more fully explained hereinafter.

Further, the switch 100 comprises a unitary contact bank 142 suitably secured in a recess provided in the bottom wall 102 of the support 101, the end wall 104 of the support 101 having a connecting recess provided therein in order to facilitate placement and removal of the contact bank 142. The contact bank 142 comprises eleven laterally spaced-apart and longitudinally extending rows of contact sets, the first row of contact sets being indicated at 143. Each row of contact sets comprises eleven individual con-

tact sets, the first contact set in the first row of contact sets 143 being indicated at 29A. The individual rows of contact sets are suitably secured together by an arrangement comprising a number of laterally extending screws 144. Also, the individual contacts in each contact set in each row of contact sets are insulated from each other by a plurality of longitudinally extending interposed strips of insulation 145 and 146, the insulating strip 146 being centrally disposed with respect to the row of contact sets and constituting a guide strip.

Further, the switch 100 comprises an arrangement including a shift magnet 33A for controlling the movements of the carriage 106 and the slide 127. The shift magnet 33A comprises a core 147, a field element 148 and a movable armature 149, the armature 149 being pivotally mounted on the outer end of the field element 148 by a pivot pin 150. Also, the core 147 carries an operating winding 151 and a copper sleeve 152, the copper sleeve 152 rendering the armature 149 slow to release after the operating winding 151 has been deenergized. The core 147 is suitably secured to a bracket 152' which in turn is suitably secured to the end wall 103 of the support 101 by an arrangement comprising two screws 153. The armature 149 is normally biased in a counterclockwise direction about the pivot pin 150, as viewed in Fig. 2, by an arrangement including a coil spring 154 extending between the armature 149 and the field element 148. The armature 149 comprises an upwardly and outwardly extending finger 155 which normally projects into the annular groove 119 formed in the outer surface of the tubular member 113. Also, the armature 149 comprises an outwardly extending arm 156 which supports the outer end of a guide bar 157, the guide bar 157 being substantially triangular in cross-section. The inner end of the guide bar 157 is pivotally mounted by a pivot pin 158 to a bracket 159 which in turn is suitably secured by an arrangement, including a screw 160, to the end wall 104 of the support 101. At this point it is noted that the guide bar 157 is adapted to be pivoted in a clockwise direction about the pivot pin 158, as viewed in Fig. 3, into engagement with one of the notches provided in the ratchet wheel 118 carried by the tubular member 113, for a purpose more fully explained hereinafter.

Further, the switch 100 comprises four sets of switch springs 40A, 50A, 60A and 70A, the individual switch springs in the set of switch springs 40A being suitably secured to the bottom wall 102 of the support 101 and insulated from each other, and the individual switch springs in the set of switch springs 50A being suitably secured to the bottom wall 102 of the support 101 and insulated from each other. Also, the individual switch springs in the set of switch springs 60A are suitably secured to a bracket 161 suitably fixed to the bottom wall 102 of the support 101 and insulated from each other. Finally, the individual switch springs in the set of switch springs 70A are suitably secured to the end wall 104 of the support 101 and insulated from each other. The set of switch springs 40A constitutes a first motion normal switch cooperating with the contact control projection 140 provided on the lower end of the side piece 129 carried by the slide 127; while the set of switch springs 50A constitutes a first motion limit switch cooperating with the contact control projection 141 provided on the lower end of the side piece 130 car-

ried by the slide 127. The set of switch springs 60A constitutes a second motion normal switch cooperating with the shelf 121 of the carriage 106; while the set of switch springs 70A constitutes a second motion limit switch cooperating with the shelf 121 of the carriage 106. Also, a set of switch springs 35A is operatively associated with the armature 149 of the shift magnet 30A, the individual switch springs of the set of switch springs 35A being suitably secured to the field element 148 of shift magnet 30A. Further, the individual switch springs of the set of switch springs 35A are suitably insulated from each other and from the end wall 103 of the support 101.

Further the switch 100 comprises a driving arrangement including a go magnet 80A, a stop magnet 90A, a spiral leaf spring 162 and a drive shaft 15A. The spiral leaf spring 162 is wound around the enlarged section 111 of the operating shaft 105, one end of the leaf spring 162 being secured to the enlarged section 111 and the other end of the leaf spring 162 being secured to a stud 164 anchored to the end wall 104 of the support 101. The outer end of the operating shaft 105 carries a tubular collar 165 slidably mounted thereon, a pin 166 being fixed to the operating shaft 105 and arranged in a longitudinally extending slot 167 formed in the tubular collar 165. The outer end of the tubular collar 165 carries an annular flange 168 formed of magnetic material. The go magnet 80A comprises an operating winding 169 and a magnetic field element 170, the field element 170 being arranged in operative relation with respect to the annular flange 168. Similarly, the stop magnet 90A comprises an operating winding 171 and a magnetic field element 172, the field element 172 being arranged in operative relation with respect to the annular flange 168. The go magnet 80A is supported by a bracket 173 suitably secured to the end wall 104 of the support 101; while the stop magnet 90A is supported by a bracket 174 suitably secured to the end wall 104 of the support 101. Further, a stub shaft 175 is suitably journaled in a bracket 176 which is suitably secured to the bracket 173. The inner end of the stub shaft 175 carries an annular drive plate 177 formed of resilient material, such as rubber, leather or the like, which cooperates with the annular flange 168. The outer end of the stub shaft 175 carries a bevel gear 178 arranged in driven relation with respect to an associated bevel gear 179 carried by the drive shaft 15A. It is noted that the drive shaft 15A is common to a plurality of switches of the character of the switch 100 and is suitably journaled in an external support 180. Preferably, the drive shaft 15A is driven in a counter-clockwise direction, as viewed in Fig. 1, by a constant speed motor, not shown, such as a synchronous motor, whereby the speed of rotation of the drive shaft 15A is maintained within extremely close limits. It is noted that the bevel gear 178 is arranged in constant meshing relation with the bevel gear 179, whereby the stub shaft 175 is constantly driven in a clockwise direction, as viewed in Fig. 2, by the drive shaft 15A.

At this point it is noted that the switch 100 as a whole is supported in cooperating relation with the drive shaft 15A upon an external support, not shown, whereby the bevel gear 178 is arranged in meshing relation with the bevel gear 179, as previously noted. Also, the switch 100 may be removed as a whole from its external support relative to the drive shaft 15A, thereby to facili-

tate replacement or repair thereof. Further, in this connection, it is pointed out that the contact bank 142 may also be supported externally, whereby the support 101 of the switch 100 may be moved relative thereto; on the other hand, the contact bank 142 may be fixed to the support 101 of the switch 100 if desired.

When the switch 100 is completely released the winding 169 of the go magnet 80A and the winding 171 of the stop magnet 90A are deenergized; the operating shaft 105 is biased in a counter-clockwise direction, as viewed in Fig. 2, by the spiral leaf spring 162; and the stub shaft 175 is driven at a constant speed in the clockwise direction, as viewed in Fig. 2, by the constantly rotating drive shaft 15A. When the switch 100 is thus completely released the tubular collar 165 occupies its retracted position toward the left, as viewed in Fig. 3, whereby the annular flange 168 completely disengages the annular drive plate 177. Also, at this time, the slide 127 occupies its completely retracted position toward the right, as viewed in Fig. 2, with respect to the carriage 106, thereby to retain operated the first motion normal switch 40A. Finally, at this time, the carriage 106 occupies its completely retracted position toward the left, as viewed in Fig. 3, thereby to retain operated the second motion normal switch 60A.

In order to operate the switch 100, thereby to cause the wiper set 10A to select a particular group or row of contact sets, the winding 169 of the go magnet 80A is first energized and retained energized for a corresponding given time interval, depending upon the speed of operation of the switch 100 relative to the speed of rotation of the stub shaft 175, this given time interval comprising one or more unit time intervals, as explained more fully hereinafter; at the conclusion of this given time interval the winding 169 of the go magnet 80A is deenergized and the winding 171 of the stop magnet 90A is energized. When the winding 169 of the go magnet 80A is thus energized the field element 170 thereof attracts the annular flange 168, thereby to cause the annular flange 168 to move toward the right, as viewed in Fig. 3, into frictional engagement with the annular drive plate 177, the pin and slot connection 166-167 between the operating shaft 105 and the tubular collar 165 accommodating this movement of the tubular collar 165 and the annular flange 168 carried thereby. When the annular flange 168 is thus moved by the go magnet 80A into frictional engagement with the annular drive plate 177 the operating shaft 105 is rotated in a clockwise direction, as viewed in Fig. 2, with the stub shaft 175, thereby to cause the spiral leaf spring 162 to be wound up.

At this time, the winding 151 of the shift magnet 30A is deenergized, whereby the armature 149 occupies its normal position, being biased in a counterclockwise direction about the pivot pin 150, as viewed in Fig. 2, by the coil spring 154. Accordingly, the finger 155 carried by the armature 149 is disposed in the annular groove 119 provided in the outer surface of the tubular member 113, thereby positively to prevent longitudinal movement of the tubular member 113 along the outer surface of the enlarged section 111 of the operating shaft 105 at this time. Also, at this time, the outer end of the guide bar 157 supported by the arm 156 carried by the armature 149 is disposed below the teeth in the ratchet wheel 116 carried by the tubular member 113,

thereby to permit rotation of the tubular member 113 at this time.

As the operating shaft 105 is rotated in a clockwise direction, as viewed in Fig. 2, at this time, the spiral groove 112 cut in the outer surface of the enlarged section 111 thereof acts upon the pin 114 carried by the tubular member 113, thereby to lock the tubular member 113 to the enlarged section 111 of the operating shaft 105 for rotation therewith. Accordingly, the tubular member 113 is rotated with the operating shaft 105, thereby to cause the endless chain 134 to be rotated about the sprocket wheels 115, 125 and 126 in a clockwise direction, as viewed in Fig. 2, the sprocket wheel 115 acting as a driving sprocket wheel and the sprocket wheels 125 and 126 acting as idler sprocket wheels. At the endless chain 134 is rotated in a clockwise direction the lower portion thereof is moved from the right toward the left, as viewed in Fig. 2, thereby to cause the slide 127 to be moved in guided relation with respect to the slot 122 provided in the shelf 121 of the carriage 106. As the slide 127 is moved from the right toward the left, as viewed in Fig. 2, the wiper set 10A is moved from its normal position at the right of the carriage 106 toward its off-normal position at the left of the carriage 106. As the slide 127 is thus moved it passes the outer ends of the various rows of contact sets without engagement therewith, whereby the wiper set 10A is moved progressively to select the various groups or rows of contact sets in a continuous motion and at a uniform speed.

The speed of rotation of the operating shaft 105 is so proportioned relative to the diameter of the sprocket wheel 115 and the lateral spacing between the rows of contact sets that, at the conclusion of a given unit time interval, the wiper set 10A occupies a position in longitudinal alignment with respect to the first row of contact sets 163; and at the conclusion of any number of unit time intervals between I and II the wiper set 10A occupies a position in longitudinal alignment with respect to a corresponding row of contact sets. Thus, at the conclusion of the first, second, etc., and eleventh unit time intervals the wiper set 10A occupies positions respectively disposed in longitudinal alignment with respect to the corresponding first, second, etc., and eleventh rows of contact sets.

At the conclusion of the given time interval the winding 169 of the go magnet 80A is deenergized and the winding 171 of the stop magnet 90A is energized, as previously noted, whereupon the field element 172 of the stop magnet 90A attracts the annular flange 168, causing the tubular collar 165 and the annular flange 168 carried thereby to be moved from the right toward the left, as viewed in Fig. 3, the pin and slot connection 166—167 between the operating shaft 105 and the tubular collar 165 facilitating this movement. At this time the winding 171 of the stop magnet 90A is retained energized, thereby to retain the annular flange 168 out of engagement with the annular drive plate 177 and in locked engagement with the field element 172. As long as the winding 171 of the stop magnet 90A is retained energized the annular flange 168 is retained in locked engagement with respect to the field element 172, thereby to retain the spiral leaf spring 162 in its wound condition and to prevent unwinding thereof and the consequent rotation of the operating shaft 105 in a counterclockwise direction, as viewed in Fig. 2, in a manner more fully explained hereinafter.

At the conclusion of the movement of the slide 127 from the right toward the left, as viewed in Fig. 2, with respect to the carriage 106, which motion constitutes the first motion of the switch 100, the winding 151 of the shift magnet 30A is energized. When the winding 151 of the shift magnet 30A is thus energized the armature 149 is attracted and rotated in a clockwise direction about the pivot pin 150, as viewed in Fig. 2, against the bias of the coil spring 154. When the armature 149 is thus operated the finger 155 carried thereby is moved out of engagement with the annular groove 119 provided in the outer surface of the tubular member 113, thereby to unlock the tubular member 113 for longitudinal movement along the outer surface of the enlarged section 111 of the operating shaft 105. Also, when the armature 149 is thus operated the arm 156 carried thereby forces the outer end of the guide bar 157 into one of the notches provided in the ratchet wheel 116, thereby to lock the tubular member 113 against rotation with the operating shaft 105.

At this point it is noted that the winding 151 of the shift magnet 30A is energized substantially simultaneously with the deenergization of the winding 169 of the go magnet 80A and the energization of the winding 171 of the stop magnet 90A; whereby the outer end of the guide bar 157 is moved into engagement with one of the notches provided in the ratchet wheel 116 prior to the time that the annular flange 168 is moved into locked engagement with the field structure 172 of the stop magnet 90A. During this brief interval of time the spiral leaf spring 162 tends to unwind, thereby to rotate the operating shaft 105 in a counterclockwise direction, as viewed in Fig. 2. However, the spiral leaf spring 162 is prevented from unwinding and the position of the operating shaft 105 is precisely centered by the action of the outer end of the guide bar 157 as it is forced by the arm 156 carried by the armature 149 into one of the notches provided in the ratchet wheel 116. This arrangement not only positively prevents unwinding of the helical leaf spring 162, as previously explained, but it also positively insures that the wiper set 10A occupies a position in precise longitudinal alignment with respect to the selected row of contact sets.

Also, when the armature 149 of the shift magnet 30A is thus operated the set of switch springs 35A is operated for a purpose more fully explained hereinafter.

After the switch 100 has been operated in the manner described above, thereby to select one of the rows of contact sets, in order further to operate the switch 100 to select a particular contact set in the previously selected row of contact sets, the winding 171 of the stop magnet 90A is first deenergized and the winding 169 of the go magnet 80A is energized for a corresponding given time interval depending upon the speed of operation of the switch 100 relative to the speed of rotation of the stub shaft 175, this given time interval comprising one or more unit time intervals, as previously explained. At the conclusion of this given time interval the winding 169 of the go magnet 80A is deenergized and the winding 171 of the stop magnet 90A is energized. When the winding 171 of the stop magnet 90A is thus deenergized the field element 172 releases the annular flange 168; and when the winding 169 of the go magnet 80A is thus energized the field element 170 attracts the annular flange

168, thereby to clutch the annular flange 168 to the annular drive plate 177 in the manner previously explained; whereby the operating shaft 105 is again rotated in the clockwise direction, as viewed in Fig. 2, with the stub shaft 175, thereby to cause the spiral leaf spring 162 to be further wound up.

At this time, the winding 151 of the shift magnet 30A is energized and the armature 149 occupies its operated position, thereby to retain the guide bar 157 in engagement with the notch provided in the ratchet wheel 116 carried by the tubular member 113 in order positively to prevent rotation of the tubular member 113 with the operating shaft 105. Accordingly, at this time, the spiral groove 112 cut in the outer surface of the enlarged section 111 of the operating shaft 105 acts upon the pin 114 carried by the tubular member 113, thereby to cause the pin 114 to ride in the spiral groove 112. As the pin 114 carried by the tubular member 113 rides in the spiral groove 112 cut in the outer surface of the enlarged section 111 of the operating shaft 105, the tubular member 113 is slid longitudinally along the enlarged section 111 from the left toward the right, as viewed in Fig. 3. As the tubular member 113 is slid from the left toward the right, as viewed in Fig. 3, the notch provided in the ratchet wheel 116 carried thereby slides in engagement with the guide bar 157, thereby positively to prevent rotation of the tubular member 113 and continues sliding thereof along the enlarged section 111 of the operating shaft 105.

As the tubular member 113 is slid longitudinally along the outer surface of the enlarged section 111 of the operating shaft 105 from the left toward the right, as viewed in Fig. 3, the carriage 106 is moved therewith due to the fact that the walls adjacent the semicircular recess 120 provided in the upper portion thereof straddle the annular groove 118 provided in the outer surface of the tubular member 113. Accordingly, the carriage 106 is slid longitudinally with the tubular member 113 from the left toward the right, as viewed in Fig. 3, the tubular members 109 and 110 secured to the opposite sides of the carriage 106 respectively sliding along the guide bars 107 and 108. As the carriage 106 is slid longitudinally from the left toward the right, as viewed in Fig. 3, the sprocket wheels 125 and 126 are slid therewith along the guide bars 107 and 108, respectively, and the slide 127 is moved therewith. When the slide 127 is moved from the left toward the right, as viewed in Fig. 3, the spaced-apart guide members 137 of the wiper set 10A carried thereby receive the guide strip 146 of the selected row of contact sets therebetween, thereby positively to guide the wiper set 10A in its sliding movement with respect to the associated row of contact sets. As the wiper set 10A is thus moved from the left toward the right, as viewed in Fig. 3, it progressively engages the individual contact sets in the previously selected row of contact sets. As previously noted, the line wipers of the wiper set 10A successively engage and disengage the line contacts in the associated contact sets; while the control wiper bridges the control contacts in the associated contact sets, for a purpose more fully explained hereinafter.

The speed of rotation of the operating shaft 105 is so proportioned relative to the pitch of the spiral groove 112 cut in the enlarged section 111 thereof and the longitudinal spacing between the individual contact sets in the row of contact

sets that, at the conclusion of a given unit time interval, the wiper set 10A engages the first contact set in the previously selected row of contact sets, and, at the conclusion of any number of unit time intervals between 1 and 11, the wiper set 10A engages a corresponding individual contact set in the previously selected row of contact sets. Thus, at the conclusion of the first, second, etc., and eleventh unit time intervals the wiper set 10A engages the corresponding first, second, etc., and eleventh individual contact sets in the previously selected row of contact sets.

At the conclusion of the given time interval the winding 168 of the go magnet 80A is de-energized and the winding 171 of the stop magnet 90A is energized, as previously noted, whereupon the field element 172 of the stop magnet 90A attracts the annular flange 168, thereby to lock the spiral leaf spring 162 against unwinding and the consequent rotation of the operating shaft 105 in a counterclockwise direction, as viewed in Fig. 2.

At this time, the wiper set 10A has selected a particular row of contact sets, corresponding to the first time interval mentioned, and a particular contact set in the selected row of contact sets, corresponding to the second time interval mentioned, thereby to establish a connection between the wiper set 10A and the last-mentioned contact set. The switch 100 is retained in its operated position as long as the winding 171 of the stop magnet 90A is retained energized, thereby to prevent unwinding of the helical leaf spring 162, in an obvious manner.

It is noted that during the first motion of the switch 100, when the slide 127 is moved laterally from its normal position at the right toward the left, as viewed in Fig. 2, the first motion normal switch 40A is operated. In the event that the slide 127 is moved laterally from the right toward the left, as viewed in Fig. 2, to a position disposed in longitudinal alignment with the eleventh row of contact sets, the first motion limit switch 50A is operated. Similarly, during the second motion of the switch 100, when the carriage 106 is moved longitudinally from its normal position at the left toward the right, as viewed in Fig. 3, the second motion normal switch 60A is operated. In the event that the carriage 106 is moved longitudinally from the left toward the right, as viewed in Fig. 3, into engagement with the eleventh contact set in the previously selected row of contact sets, the second motion limit switch 70A is operated.

In order completely to release the switch 100 after it has been fully operated in the manner previously explained, it is only necessary to de-energize the winding 171 of the stop magnet 90A, whereupon the annular flange 168 is unlocked with respect to the field element 172, thereby to permit unwinding of the spiral leaf spring 162 and the consequent rotation of the operating shaft 105 in a counterclockwise direction, as viewed in Fig. 2. At this time the winding 151 of the shift magnet 30A is retained energized, thereby to retain the armature 149 thereof in its operated position. The operated armature 149 retains the guide bar 157 in the associated notch provided in the ratchet wheel 116 carried by the tubular member 113, in the manner previously explained. Accordingly, as the operating shaft 105 is rotated in a counterclockwise direction, as viewed in Fig. 2, the tubular member 113 is slid longitudinally along the

outer surface of the enlarged section 111 of the operating shaft 105 from the right toward the left, as viewed in Fig. 3, due to the cooperation between the pin 114 carried by the tubular member 113 and the associated engaged spiral groove 112 cut in the outer surface of the enlarged section 111 of the operating shaft 105, in the manner previously explained.

When the tubular member 113 is returned to its normal position and, consequently, the carriage 106 to its normal position at the left, as viewed in Fig. 3, the winding 151 of the shift magnet 30A is deenergized, whereupon the armature 149 is released and rotated in a counterclockwise direction about the pivot pin 150, as viewed in Fig. 2, by the coil spring 154. When the armature 149 is thus restored the finger 155 carried thereby is returned into the annular groove 119 disposed in the outer surface of the tubular member 113, thereby to lock the tubular member 113 against longitudinal sliding on the outer surface of the enlarged section 111 of the operating shaft 105 incident to the next cycle of operation of the switch 100. Also, when the armature 149 is thus released the outer end of the guide bar 157 is lowered out of engagement with the associated notch in the ratchet wheel 116, thereby to unlock the tubular member 113 for rotation, in a counterclockwise direction, with the operating shaft 105. The spiral leaf spring 162 then rotates the operating shaft 105 and the tubular member 113 in a counterclockwise direction, as viewed in Fig. 2, whereupon the endless chain 134 is rotated in a counterclockwise direction, in order to restore the slide 127 to its normal position at the right, as viewed in Fig. 2.

When the carriage 106 is returned to its normal position at the left, as viewed in Fig. 3, the second motion normal switch 60A is operated; and when the slide 127 is moved to its normal position at the right, as viewed in Fig. 2, the first motion normal switch 40A is operated. Of course, the second motion limit switch 70A is operated when the carriage 106 is moved from its final right position, as viewed in Fig. 3, in the event that the carriage 106 was so moved as to operate the second motion limit switch 70A initially; similarly, the first motion limit switch 50A is operated when the slide 127 is moved from its final left position, as viewed in Fig. 2, in the event that the slide 127 was so moved as to operate the first motion limit switch 50A initially. Also, when the armature 149 of the shift magnet 30A is released the set of switch springs 35A is operated in an obvious manner. At this time, the switch 100 is completely released and available for further use.

Construction and operation of the modified form of the automatic switch

Referring now more particularly to Figs. 4 and 5 of the drawings there is illustrated a modified form of an automatic switch 400 embodying the present invention, which comprises a support 401 including side walls 402 and 403, a rear wall 404, a bottom wall 405, and an operating shaft 406. The operating shaft 406 is substantially centrally disposed between the side walls 402 and 403 of the support 401, the lower end of the operating shaft 406 being suitably journaled in a step bearing 407 suitably fixed to the bottom wall 405 of the support 401. The upper end of the operating shaft 406 is suitably journaled in a bearing collar 408 which in turn is suitably fixed in an opening provided in a transverse

angle plate 409 extending between and suitably secured to the side walls 402 and 403 of the support 401. Also, the switch 400 comprises a rotatable and longitudinally slideable carriage 410 including a cylindrical side wall 411, an annular bottom wall 412 and an annular top wall 413 suitably secured together to provide a rigid construction. The carriage 410 surrounds the operating shaft 406 and is adapted for longitudinal sliding movement thereon, the operating shaft 406 extending through aligned slide bearings respectively provided in the annular bottom wall 412 and the annular top wall 413. The carriage 410 is operatively connected to the operating shaft 406 by an arrangement comprising a pin 414 secured to the operating shaft 406 and a semi-spiral or helical groove 415 cut in the outer surface of the cylindrical side wall 411, the pin 414 projecting into the spiral groove 415.

Further, the switch 400 comprises a contact controlling member 10B in the form of a wiper set which is carried by the top wall 413 of the carriage 410. At this point it is noted that the control wiper of the wiper set 10B is of the bridging type; while the line wipers thereof are not of the bridging type, this arrangement being utilized for a purpose more fully explained hereinafter. The individual wipers of the wiper set 10B are suitably secured together and to the top wall 413 of the carriage 410 and are suitably insulated from each other and from the top wall 413 by interposed strips of insulation, not shown. Also, the switch 400 comprises a unitary contact bank 416, including a semi-cylindrical supporting plate 417 suitably secured to the side walls 402 and 403 of the support 401 and eleven circumferentially spaced-apart and longitudinally extending rows of contact sets, the first row of contact sets being indicated at 418. Each row of contact sets comprises eleven individual contact sets, the first contact set in the first rows of contact sets 418 being indicated at 20B. The individual row of contact sets are suitably secured in radially disposed openings 419 provided in the semi-cylindrical supporting plate 417. Also, the individual contacts in each contact set in each row of contact sets are insulated from each other by a plurality of longitudinally extending interposed strips of insulation 420 and 421, the insulating strip 421 being centrally disposed with respect to the row of contact sets and constituting a guide strip. At this point it is noted that the individual wipers in the wiper set 10B are arranged in pairs; and the individual contacts in each contact set in each row of contact sets are arranged in pairs; whereby each pair of wipers in the wiper set 10B is adapted to shunt or connect together a corresponding pair of individual contacts in each contact set in each row of contact sets.

Further, the switch 400 comprises an arrangement including a shift magnet 30B for controlling the rotary and longitudinal movements of the carriage 410. The shift magnet 30B comprises a core 422, a field element 423 and a movable armature 424, the armature 424 being pivotally mounted on the outer end of the field element 423 by a pivot pin 425. Also, the core 422 carries an operating winding 426 and a copper sleeve 427, the copper sleeve 427 rendering the armature 424 slow to release after the operating winding 426 has been deenergized. The core 422 and the field element 423 are suitably secured to a bracket 428 which in turn is suit-

ably fixed to the side wall 403 of the support 401. Further, the field element 423 carries a set of switch springs 35B which is operatively associated with the armature 424, thereby to bias the armature 424 in a counterclockwise direction about the pivot pin 425, as viewed in Fig. 5. Finally, the armature 424 carries an operating arm 429, the outer end of which is disposed below the bottom wall 412 of the carriage 410. At this point it is noted that the armature 424 is adapted to be rotated in a clockwise direction about the pivot pin 425, as viewed in Fig. 5, thereby to cause the operating arm 429 thereof to lift or slide the carriage 410 longitudinally of the operating shaft 406. Finally, in this connection, it is noted that the upper end of the spiral groove 415 cut in the outer surface of the cylindrical side wall 411 of the carriage 410 terminates in a substantially straight portion 430 which is normally disposed in engagement with the pin 414 carried by the operating shaft 406. Accordingly, it will be understood that when the carriage 410 is lifted or slid longitudinally of the operating shaft 406 the pin 414 carried by the operating shaft 406 rides out of the straight portion 430 of the spiral groove 415 into the spiral or helical portion thereof, in an obvious manner.

Further, the switch 400 comprises four sets of switch springs 40B, 50B, 60B and 70B, the individual switch springs in the set of switch springs 40B being suitably secured to a transverse bracket 431 extending between and suitably fixed to the side walls 402 and 403 of the support 401 and insulated from each other, and the individual switch springs in the set of switch springs 50B being suitably secured to the bracket 431 and insulated from each other. Also, the individual switch springs in the set of switch springs 60B are suitably secured to the bracket 431 and insulated from each other. Finally, the individual switch springs in the set of switch springs 70B are suitably secured to the plate 409 and insulated from each other. The set of switch springs 40B constitutes a first motion normal switch cooperating with a projection 433 fixed to the outer surface of the cylindrical side wall 411 of the carriage 410; while the set of switch springs 60B constitutes a first motion limit switch cooperating with the projection 433. The set of switch springs 60B constitutes a second motion normal switch cooperating with the top wall 413 of the carriage 410; while the set of switch springs 70B constitutes a second motion limit switch cooperating with the top wall 413.

Further, the switch 400 comprises a driving arrangement including a go magnet 80B, a stop magnet 90B, a spiral leaf spring 434 and a drive shaft 15B. The spiral leaf spring is wound around the operating shaft 406, one end of the leaf spring 434 being secured to the operating shaft 406 and the other end of the leaf spring 434 being secured to a stud 435 anchored to the bottom wall 405 of the support 401. The upper end of the operating shaft 406 carries a tubular collar 436 slidably mounted thereon, a pin 437 being fixed to the operating shaft 406 and arranged in a longitudinally extending slot 438 formed in the tubular collar 436. The lower end of the tubular collar 436 is normally supported upon the bearing collar 408. The outer end of the tubular collar 436 carries an annular flange 440 formed of magnetic material. The go magnet 80B comprises an operating winding 441 and

5 a magnetic field element 442, the field element 442 being arranged in operative relation with respect to the annular flange 440. Similarly, the stop magnet 90B comprises an operating winding 443 and a magnetic field element 444, the field element 444 being arranged in operative relation with respect to the annular flange 440. The go magnet 80B is supported by a bracket 445 suitably secured to a transverse angle plate 446 extending between and suitably fixed to the side walls 402 and 403 of the support 401; while the stop magnet 90B is supported by a bracket 447 suitably secured to the plate 446. Further, a stub shaft 448 is suitably journaled in a substantially U-shaped bracket 449 which in turn is suitably fixed to the plate 446. The inner end of the stub shaft 448 carries an annular drive plate 450 formed of resilient material, such as rubber, leather or the like, which cooperates with the annular flange 440. The outer end of the stub shaft 448 carries a bevel gear 451 arranged in driven relation with respect to an associated bevel gear 452 carried by the drive shaft 15B. It is noted that the drive shaft 15B is common to a plurality of switches of the character of the switch 400 and is suitably journaled in an external support, not shown. Preferably, the drive shaft 15B is driven in a clockwise direction, as viewed in Fig. 5, by a constant speed motor, not shown, such as a synchronous motor, whereby the speed of rotation of the drive shaft 15B is maintained within extremely close limits. It is noted that the bevel gear 451 is arranged in constant meshing relation with the bevel gear 452, 20 whereby the stub shaft 448 is constantly driven in a clockwise direction, as viewed in Fig. 4, by the drive shaft 15B.

Further, the switch 400 comprises a release arrangement including a release magnet 85B and 25 a ratchet wheel 453, the ratchet wheel 453 being fixed to the operating shaft 406. The release magnet 85B comprises a core 454, a field element 455 suitably secured to the bottom wall 405 of the support 401, and an armature 456, the armature 456 being pivotally mounted on the outer end of the field element 455 by a pivot pin 457. The core 454 carries an operating winding 458 and a copper sleeve 459, the copper sleeve rendering the armature 456 slow to operate after the operating winding 458 is energized. The armature 456 is biased in a clockwise direction about the pivot pin 457, as viewed in Fig. 4, by an arrangement comprising a set of switch springs 95B suitably secured to the field element 455, the individual switch springs in the set of switch springs 95B being suitably insulated from each other and from the field element 455 by interposed strips of insulation 460. The outer end of the armature 456 carries a pawl 461 operatively associated with the ratchet wheel 453, whereby the ratchet wheel 453 may be freely rotated in a clockwise direction, as viewed in Fig. 4, when the armature 456 is released, but may be rotated in the counterclockwise direction, as viewed in Fig. 4, only when the armature 456 is operated.

At this point it is noted that the switch 400 as a whole is supported in cooperating relation with the drive shaft 15B upon an external support, not shown, whereby the bevel gear 451 is arranged in meshing relation with the bevel gear 452, as previously noted. Also, the switch 400 may be removed as a whole from its external support relative to the drive shaft 15B, thereby to facilitate replacement or repair thereof.

When the switch 400 is completely released the

winding 441 of the go magnet 80B and the winding 443 of the stop magnet 90B are deenergized; the operating shaft 406 is biased in a counterclockwise direction, as viewed in Fig. 4, by the spiral leaf spring 434; and the stub shaft 448 is driven at a constant speed in the clockwise direction, as viewed in Fig. 4, by the constantly rotating drive shaft 15B. When the switch 409 is thus completely released the tubular collar 436 occupies its retracted position toward the bottom, as viewed in Fig. 5, whereby the annular flange 440 completely disengages the annular drive plate 450. Also, at this time, the carriage 410 occupies its completely retracted position in a counterclockwise direction, as viewed in Fig. 4, with respect to the contact bank 416, and its completely retracted position toward the bottom, as viewed in Fig. 5, with respect to the contact bank 416.

In order to operate the switch 409, thereby to cause the wiper set 10B to select a particular group or row of contact sets, the winding 441 of the go magnet 80B is first energized and retained energized for a corresponding given time interval, depending upon the speed of operation of the switch 409 relative to the speed of rotation of the stub shaft 448, this given time interval comprising one or more unit time intervals, as explained more fully hereinafter; at the conclusion of this given time interval the winding 441 of the go magnet 80B is deenergized and the winding 443 of the stop magnet 90B is energized. When the winding 441 of the go magnet 80B is thus energized the field element 442 thereof attracts the annular flange 440, thereby to cause the annular flange 440 to move toward the top, as viewed in Fig. 5, into frictional engagement with the annular drive plate 450, the pin and slot connection 437—438 between the operating shaft 406 and the tubular collar 436 accommodating this movement of the tubular collar 436 and the annular flange 440 carried thereby. When the annular flange 440 is thus moved by the go magnet 80B into frictional engagement with the annular drive plate 450 the operating shaft 406 is rotated in a clockwise direction, as viewed in Fig. 4, with the stub shaft 448, thereby to cause the spiral leaf spring 434 to be wound up.

At this time, the winding 426 of the shift magnet 30B is deenergized, whereby the armature 424 occupies its normal position, being biased in a counterclockwise direction about the pivot pin 425, as viewed in Fig. 5, by the set of switch springs 35B. Accordingly, the carriage 410 occupies its retracted position toward the bottom, as viewed in Fig. 5, whereby the pin 414 carried by the operating shaft 406 engages the straight portion 430 of the spiral groove 415 cut in the cylindrical side wall 411 of the carriage 410.

As the operating shaft 406 is rotated in a clockwise direction, as viewed in Fig. 4 at this time, the pin 440 carried by the operating shaft 406 acts upon the straight portion 430 of the spiral groove 415 cut in the cylindrical side wall 411 of the carriage 410, thereby to lock the carriage 410 to the operating shaft 406 for rotation therewith. Accordingly, the carriage 410 is rotated with the operating shaft 406, thereby to cause the wiper set 10B to be rotated below the lower ends of the various rows of contact sets without engagement therewith, whereby the wiper set 10B is moved progressively to select the various rows of contact sets in a continuous motion and at a uniform speed. The speed of rotation of the operating shaft 406 is so proportioned rel-

ative to the circumferential spacing between the rows of contact sets that, at the conclusion of a given unit time interval, the wiper set 10B occupies a position in longitudinal alignment with respect to the first row of contact sets 418; and at the conclusion of any number of time intervals between 1 and 11 the wiper set 10B occupies a position in longitudinal alignment with respect to a corresponding row of contact sets. Thus, at the conclusion of the first, second, etc., and eleventh unit time intervals, the wiper set 10B occupies positions respectively disposed in longitudinal alignment with respect to the corresponding first, second, etc., and eleventh rows of contact sets.

At the conclusion of the given time interval the winding 441 of the go magnet 80B is deenergized and the winding 443 of the stop magnet 90B is energized, as previously noted, whereupon the field element 444 of the stop magnet 90B attracts the annular flange 440, causing the tubular collar 436 and the annular flange 440 carried thereby to be moved toward the bottom, as viewed in Fig. 5, the pin and slot connection 437—438 between the operating shaft 406 and the tubular collar 436 facilitating this movement. At this time, the winding 443 of the stop magnet 90B is retained energized, thereby to retain the annular flange 440 out of engagement with the annular drive plate 450 and in locked engagement with the field element 444. As long as the winding 443 of the stop magnet 90B is retained energized, the annular flange 440 is retained in locked engagement with respect to the field element 444, thereby to retain the spiral leaf spring 434 in its wound condition and to prevent unwinding thereof and the consequent rotation of the operating shaft 406 in a counterclockwise direction, as viewed in Fig. 4, in a manner more fully explained hereinafter. Also, at this time, the winding 458 of the release magnet 85B is deenergized, whereby the armature 456 occupies its released position, being biased in a clockwise direction about the pivot pin 457, as viewed in Fig. 4, by the set of switch springs 95B. Thus, the pawl 461 carried by the armature 456 engages one of the notches provided in the ratchet wheel 453, thereby positively to retain the spiral leaf spring 434 in its wound condition and positively to prevent unwinding thereof and the consequent rotation of the operating shaft 406 in a counterclockwise direction, as viewed in Fig. 2.

At the conclusion of the rotary movement of the carriage 410 in a clockwise direction, as viewed in Fig. 4, which motion constitutes the first motion of the switch 409, the winding 426 of the shift magnet 30B is energized. When the winding 426 of the shift magnet 30B is thus energized the armature 424 is attracted and rotated in a clockwise direction about the pivot pin 425, as viewed in Fig. 5, against the bias of the set of switch springs 35B. When the armature 424 is thus operated the arm 429 carried thereby is forced against the bottom wall 412 of the carriage 410 and exerts a lifting action thereon, whereby the carriage 410 is lifted or slid longitudinally toward the top, as viewed in Fig. 5, thereby to disengage the pin 414 carried by the operating shaft 406 and the straight portion 430 of the spiral groove 415 cut in the cylindrical side wall 411 of the carriage 410, and to engage the pin 414 and the helical portion of the spiral groove 415 cut in the cylindrical side wall 411. Also, when the carriage 410 is thus lifted or moved longitudinally toward the top, as viewed

in Fig. 5, the guide strip 421 of the previously selected row of contact sets is forced between the individual wipers of the wiper set 10B, thereby positively to lock the wiper set 10B and the carriage 410 against further rotation in the clockwise direction, as viewed in Fig. 4. At this time, the carriage 410 is adapted for longitudinal sliding movement toward the top, as viewed in Fig. 5, along the operating shaft 406.

At this point, it is noted that the winding 426 of the shift magnet 30B is energized substantially simultaneously with the deenergization of the winding 441 of the go magnet 80B and the energization of the winding 443 of the stop magnet 90B. During the brief interval of time between the deenergization of the winding 441 of the go magnet 80B and the effective energization of the winding 443 of the stop magnet 90B, the spiral leaf spring 434 tends to unwind, thereby to rotate the operating shaft 406 in a counterclockwise direction, as viewed in Fig. 4. However, the spiral leaf spring 434 is prevented from effective unwinding; and the position of the operating shaft 406 and, consequently, the carriage 410 and the wiper set 10B carried thereby is precisely centered by the action of the pawl 461 carried by the armature 456. This arrangement not only positively prevents effective unwinding of the spiral leaf spring 434, as previously explained, but it also positively insures that the wiper 10B occupies a position in precise longitudinal alignment with respect to the selected row of contact sets when the winding 426 of the shift magnet 30B is effectively energized and the armature 424 is operated, thereby insuring that the guide strip 421 is received in proper alignment between the individual wipers of the wiper set 10B.

Also, when the armature 424 of the shift magnet 30B is thus operated the set of switch springs 35B is operated, for a purpose more fully explained hereinafter.

After the switch 400 has been operated in the manner described above, thereby to select one of the rows of contact sets, in order further to operate the switch 400 to select a particular contact set in the previously selected row of contact sets, the winding 443 of the stop magnet 90B is first deenergized and the winding 441 of the go magnet 80B is energized for a corresponding given time interval depending upon the speed of operation of the switch 400 relative to the speed of rotation of the stub shaft 448, this given time interval comprising one or more unit time intervals, as previously explained. At the conclusion of this given time interval the winding 441 of the go magnet 80B is deenergized and the winding 443 of the stop magnet 90B is energized. When the winding 443 of the stop magnet 90B is thus deenergized the field element 444 releases the annular flange 440; and when the winding 441 of the go magnet 80B is thus energized the field element 442 attracts the annular flange 440, thereby to clutch the annular flange 440 to the annular drive plate 458, in the manner previously explained; whereby the operating shaft 406 is again rotated in the clockwise direction, as viewed in Fig. 4, with the stub shaft 448, thereby to cause the spiral leaf spring 434 to be further wound up.

At this time the winding 426 of the shift magnet 30B is energized and the armature 424 occupies its operated position, thereby to retain the carriage 410 in its lifted position, as viewed in Fig. 5. Accordingly, at this time, the helical portion of the spiral groove 415 cut in the cylin-

drical side wall 411 of the carriage 410 operatively engages the pin 414 carried by the operating shaft 406, thereby to cause the pin 414 to ride in the spiral groove 415. As the pin 414 carried by the operating shaft 406 rides in the spiral groove 415 cut in the cylindrical side wall 411 of the carriage 410, the carriage 410 is lifted or slid longitudinally toward the top, as viewed in Fig. 5, along the operating shaft 406. As the carriage 410 is slid longitudinally toward the top, as viewed in Fig. 5, the guide strip 421 of the previously selected row of contact sets is disposed between the individual wipers of the wiper set 10B carried by the carriage 410, thereby positively to prevent rotation of the carriage 410 and to insure continuous longitudinal sliding of the carriage 410 and the wiper set 10B carried thereby toward the top, as viewed in Fig. 5.

As the wiper set 10B is thus moved longitudinally toward the top, as viewed in Fig. 5, it progressively engages the individual contact sets in the previously selected row of contact sets. As previously noted, the line wipers of the wiper set 10B successively engage and disengage the line contacts in the associated contact sets; while the control wiper thereof bridges the control contacts in the associated contact sets for a purpose more fully explained hereinafter.

The speed of rotation of the operating shaft 406 is so proportioned relative to the pitch of the spiral groove 415 cut in the cylindrical side wall 411 of the carriage 410 and the longitudinal spacing between the individual contact sets in the row of contact sets that at the conclusion of a given unit time interval the wiper set 10B engages the first contact set in the previously selected row of contact sets, and at the conclusion of any number of unit time intervals between 1 and 11, the wiper set 10B engages a corresponding individual contact set in the previously selected row of contact sets. Thus at the conclusion of the first, second, etc., and eleventh unit time intervals the wiper set 10B engages the corresponding first, second, etc., and eleventh individual contact sets in the previously selected row of contact sets.

At the conclusion of the given time interval the winding 441 of the go magnet 80B is deenergized and the winding 443 of the stop magnet 90B is energized as previously noted, whereupon the field element 444 of the stop magnet 90B attracts the annular flange 440, thereby to lock the spiral leaf spring 434 against unwinding and the consequent rotation of the operating shaft 406 in a counterclockwise direction, as viewed in Fig. 4. During the brief interval of time between the deenergization of the winding 441 of the go magnet 80B and the effective energization of the winding 443 of the stop magnet 90B the spiral leaf spring 434 tends to unwind, thereby to rotate the operating shaft 406 in a counterclockwise direction, as viewed in Fig. 4. However, the spiral leaf spring 434 is prevented from effective unwinding; and the position of the operating shaft 406 and, consequently, the longitudinal position of the carriage 410 and the wiper set 10B carried thereby is precisely centered by the action of the pawl 461 carried by the armature 456 of the release magnet 85B. This arrangement not only positively prevents effective unwinding of the spiral leaf spring 434, as previously explained, but it also positively insures that the wiper set 10B occupies a position in centered engagement with respect to the

selected contact set in the previously selected row of contact sets.

At this time the wiper set 10B has selected a particular row of contact sets, corresponding to the first time interval mentioned, and a particular contact set in the selected row of contact sets, corresponding to the second time interval mentioned, thereby to establish a shunt connection between the pairs of individual contacts in the selected contact set. The switch 403 is retained in its operated position so long as the winding 443 of the stop magnet 90B is retained energized, and the winding 458 of the release magnet 85B is retained deenergized, thereby to prevent unwinding of the spiral leaf spring 434 in an obvious manner.

It is noted that during the first motion of the switch 403 when the carriage 410 is rotated in a clockwise direction from its normal position at the left toward the right, as viewed in Fig. 4, the first motion normal switch 40B is operated by the projection 433 carried by the cylindrical side wall 411 of the carriage 410. In the event that the carriage 410 is rotated in a clockwise direction, as viewed in Fig. 4, to a position disposed in longitudinal alignment with the eleventh row of contact sets, the first motion limit switch 50B is operated by the projection 433 carried by the cylindrical side wall 411 of the carriage 410. Similarly, during the second motion of the switch 403 when the carriage 410 is slid longitudinally from its normal position at the bottom toward the top, as viewed in Fig. 5, the second motion normal switch 60B is operated by the top wall 413 of the carriage 410. In the event that the carriage 410 is moved longitudinally toward the top, as viewed in Fig. 5, into engagement with the eleventh contact set in the previously selected row of contact sets, the second motion limit switch 70B is operated by the top wall 413 of the carriage 410.

In order completely to release the switch 403 after it has been fully operated in the manner previously explained, it is necessary not only to deenergize the winding 443 of the stop magnet 90B but also to energize the winding 458 of the release magnet 85B. When the stop magnet 90B is thus released the operating shaft 406 is rendered free to rotate in the counterclockwise direction, as viewed in Fig. 4, except for the engagement between the pawl 461 and the associated notch provided in the ratchet wheel 453. When the winding 458 of the release magnet 85B is thus energized the armature 456 is operated, thereby to operate the associated set of switch springs 95B and to cause the armature 456 to be rotated in a counterclockwise direction about the pivot pin 457, as viewed in Fig. 4, whereupon the pawl 461 disengages the associated notch in the ratchet wheel 453. At this time the operating shaft 406 is free to rotate in a counterclockwise direction, as viewed in Fig. 4, and is so rotated by the spiral leaf spring 434 incident to the unwinding thereof. Accordingly, as the operating shaft 406 is rotated in a counterclockwise direction, as viewed in Fig. 4, the carriage 410 is slid longitudinally along the operating shaft 406 from the top toward the bottom, as viewed in Fig. 5, due to the co-operation between the pin 414 carried by the operating shaft 406 and the spiral groove 415 cut in the cylindrical side wall 411 of the carriage 410, in the manner previously explained.

When the carriage 410 is returned almost to its normal position at the bottom, as viewed in

Fig. 5, the winding 423 of the shaft magnet 30B is deenergized, whereupon the armature 429 is released in order to permit the carriage 410 to be moved into its normal position. When the carriage 410 is moved into its normal position at the bottom, as viewed in Fig. 5, the guide strip 431 of the previously selected row of switching springs is removed from between the individual wipers of the wiper set 10B, thereby to unlock the carriage 410 for rotation in a counterclockwise direction, as viewed in Fig. 4. Also, when the carriage 410 is returned to its normal position at the bottom, as viewed in Fig. 5, the pin 414 carried by the operating shaft 406 disengages the helical portion of the spiral groove cut in the cylindrical side wall 411 of the carriage 410 and reengages the straight portion 415 of the spiral groove 415, thereby to lock the carriage 410 against longitudinal sliding movement on the operating shaft 406 incident to the next cycle of operation of the switch 403. At this time the spiral leaf spring 434 continues to rotate the operating shaft 406 in a counterclockwise direction, as viewed in Fig. 4, whereby the carriage 410 is returned to its normal position at the left, as viewed in Fig. 4.

When the carriage 410 is returned to its normal position at the bottom, as viewed in Fig. 5, the second motion normal switch 90B is operated; and when the carriage 410 is rotated to its normal position at the left, as viewed in Fig. 4, the first motion normal switch 40B is operated. Of course, the second motion limit switch 70B is operated when the carriage 410 is moved from its final top position, as viewed in Fig. 5, in the event that the carriage 410 was so moved as to operate the second motion limit switch 70B initially; similarly, the first motion limit switch 50B is operated when the carriage 410 is moved from its final position at the right, as viewed in Fig. 4, in the event that the carriage 410 was so moved as to operate the first motion limit switch 50B initially. Also, when the armature 424 of the shift magnet 30B is released the set of switch springs 95B is operated in an obvious manner.

Finally, when the carriage 410 is returned both to its normal position at the bottom, as viewed in Fig. 5, and to its normal position at the left, as viewed in Fig. 4, the winding 458 of the release magnet 85B is deenergized, thereby to release the armature 456, whereupon the armature 456 is rotated in a clockwise direction about the pivot pin 457, as viewed in Fig. 4. At this time the set of switch springs 95B is again operated and the pawl 461 carried by the armature 456 reengages one of the notches provided in the ratchet wheel 453 carried by the operating shaft 406, whereupon the operating shaft 406 is again locked against rotation in a counterclockwise direction, as viewed in Fig. 4. At this time the switch 403 is completely released and available for further use.

65 Connection and arrangement of the telephone system

Referring now more particularly to Figs. 6 and 7 of the drawings, there is illustrated an automatic telephone system comprising an exchange having a plurality of subscriber lines extending thereto, including the subscriber lines 601 and 701 respectively extending to the subscriber substations T1 and T2. Also the exchange comprises subscriber controlled switching apparatus for setting up connections between

various subscriber lines, this switching apparatus comprising a line switch individual to each subscriber line, the line switches 602 and 702 being individual to the subscriber lines 601 and 701, respectively, a group of selectors, including the selector 600, and a plurality of groups of connectors, one group of connectors including the connector 700. The number of selectors in the group of selectors and the number of connectors in each group of connectors in the system are determined in accordance with the maximum volume of traffic the exchange is required to handle. Preferably, each of the line switches has access to each of the selectors; each of the selectors has access to each of the connectors; and each of the connectors has access to each of the subscriber lines in an associated group.

Preferably, each subscriber substation comprises substation apparatus identical to that illustrated at the subscriber substations T1 and T2; the subscriber substation apparatus at the subscriber substation T1 including a transmitter 603, a receiver 604, a hook switch 605 and a calling device 606; and the subscriber substation apparatus at the subscriber substation T2 includes a transmitter 703, a receiver 704, a hook switch 705 and a calling device 706. Preferably, the subscriber substation apparatus at each subscriber substation is entirely conventional with the exception of the calling device, while each calling device embodies the unique construction and arrangement disclosed in Bernard D. Willis Patent No. 2,222,131, granted November 19, 1940. As disclosed in the Willis patent, this calling device is so constructed and arranged that it transmits a single impulse of variable length of time duration, as contrasted with conventional calling devices which transmit a variable series of impulses, this calling device including a finger dial and having the same general external appearance of a conventional calling device.

Preferably, each line switch is identical to the line switches 602 and 702, which line switches are connected and arranged in accordance with conventional practice.

Preferably, each of the selectors is identical to the selector 600 which comprises either an automatic switch of the character of the automatic switch 100, shown in Figs. 1 to 3, inclusive, or an automatic switch of the character of the automatic switch 400, shown in Figs. 4 and 5. This automatic switch comprises a go magnet 80Y, a stop magnet 90Y, a shift magnet 30Y, a wiper set 10Y, a first motion normal switch 40Y, a first motion limit switch 50Y, a second motion normal switch 60Y, a second motion limit switch 70Y, and a set of switch springs 95Y, these elements corresponding in function to the corresponding common elements previously described in the automatic switches 100 and 400, corresponding reference characters being employed. Also, it is noted that in the event that the automatic switch 400 is embodied in the selector 600 that a release magnet 85Y and an associated set of switch springs 95Y are provided, these elements corresponding in function to the corresponding elements previously described in the automatic switch 400, corresponding reference characters being employed. Further, the selector 600 comprises a group of relays including a line relay R610, a hold relay R620, a switch relay R630, and two control relays R640 and R650, and a control network.

Preferably, each of the connectors is identical to the connector 700 which comprises either an

automatic switch of the character of the automatic switch 100, shown in Figs. 1 to 3, inclusive, or an automatic switch of the character of the automatic switch 400, shown in Figs. 4 and 5. This automatic switch comprises a go magnet 80Y, a stop magnet 90Y, a shift magnet 30Y, a wiper set 10Y, a first motion normal switch 40Y, a first motion limit switch 50Y, a second motion normal switch 60Y, a second motion limit switch 70Y, and a set of switch springs 95Y, these elements corresponding in function to the corresponding common elements previously described in the automatic switches 100 and 400, corresponding reference characters being employed. Also, it is noted that in the event the automatic switch 400 is embodied in the connector 700 that a release magnet 85Y and an associated set of switch springs 95Y are provided, these elements corresponding in function to the corresponding elements previously described in the automatic switch 400, corresponding reference characters being employed. Further, the connector 700 comprises a group of relays including a line relay R710, a hold relay R720, a test relay R730, an answer relay R740, a switch relay R750, a ring relay R760, and two control relays R770 and R780, and a control network.

The connection and arrangement of the automatic telephone system described above are disclosed and claimed in the previously mentioned copending application of Bernard D. Willis.

Operation of the apparatus incorporated in the system

The mechanical construction and arrangement of the automatic switch 100, shown in Figs. 1 to 3, inclusive, and the automatic switch 400, shown in Figs. 4 and 5, as well as the electrical connection and arrangement of the telephone system shown in Figs. 6 and 7, will best be understood from a consideration of the mode of operation of the apparatus incorporated in the system incident to the extension of a telephone connection from the subscriber substation T1 to the subscriber substation T2.

A call is initiated at the subscriber substation T1 by removing the receiver 604 of the telephone instrument thereat from its associated switch-hook, thereby to cause the hook switch 605 to operate and complete an obvious connection between the line conductors of the subscriber line 601 terminating in the line switch 602. When a connection is completed between the line conductors of the subscriber line 601, the line switch 602 operates automatically to search for a trunk extending to an idle selector, in accordance with conventional practice. Assuming that the selector 600 is the first idle selector accessible to the line switch 602, the line switch 602 operates to seize the trunk 660 extending thereto, the trunk 660 being marked as idle by the absence of potential upon the control conductor 663 thereof. When the line switch 602 seizes the trunk 660, further operation thereof is arrested and it operates to switch through, thereby to complete an obvious connection between the subscriber line 601 and the line conductors C661 and C662 of the trunk 660. When this connection is completed an obvious loop circuit is completed between the calling subscriber substation T1 and the upper and lower windings of the line relay R610 in the selector 600 by way of the line switch 602. When thus energized the line relay R610 operates to complete, at the contacts 611, a cir-

cuit for energizing in series the winding of the control relay R640 and the stop magnet 90X, this circuit extending from ground by way of the contacts 651 and 611, the winding of R640 and the stop magnet 90X to battery. Also, it is noted that the winding of the control relay R640 is normally shunted by the contacts 641 and the resistor 645, this arrangement being provided in order positively to insure that the stop magnet 90X is fully energized promptly. When thus energized, the control relay R640 operates to interrupt, at the contacts 641, the previously mentioned shunt around the winding thereof, whereby an obvious holding circuit substantially identical to that previously traced is completed for energizing in series the winding of the control relay R640 and the stop magnet 90X. When thus energized the stop magnet 90X operates, thereby to insure that the automatic switch incorporated in the selector 600 is declutched from the associated drive shaft. Also, upon operating, the line relay R610 completes at the contacts 612 an obvious circuit for energizing the winding of the hold relay R620, thereby to cause the latter relay to operate. Upon operating, the hold relay R620 completes, at the contacts 622, an obvious multiple point in the previously mentioned holding circuit for energizing in series the winding of the control relay R640 and the stop magnet 90X. Also, the hold relay R620 completes, at the contacts 621, an obvious path for applying ground potential to the control conductor C663 of the trunk 660, thereby to mark the trunk 660 as busy to the line switches having access thereto. Further, when ground potential is applied to the control conductor C663 of the trunk 660, it is applied by way of the line switch 602 to the control conductor C631 of the subscriber line 601, thereby to mark the subscriber line 601 as busy to the connectors having access thereto. At this time an operative connection is completed between the calling subscriber substation T1 and the selector 600, and the selector 600 is in readiness to receive the first digit.

The subscriber at the calling subscriber substation T1 then dials the first digit in the calling device 606 thereat, thereby to cause the previously traced connection between the calling subscriber substation T1 and the line relay R610 in the selector 600 to be interrupted, to remain interrupted for a corresponding given time interval, and then to be recompleted at the conclusion of the given time interval, the duration of the given time interval being determined by the particular digit dialed in the calling device 606 at the calling subscriber substation T1, as disclosed in the previously mentioned Willis patent. Accordingly, the line relay R610 restores, remains restored for the given time interval and then reoperates. Upon restoring, the line relay R610 completes, at the contacts 613, a circuit for energizing in series the winding of the control relay R650 and the go magnet 80X, this circuit extending from ground by way of the contacts 613 and 623, the contacts 62 of the second motion normal switch 60X, the winding of R653 and the go magnet 80X to battery. It is noted that the winding of the control relay R650 is normally shunted by the contacts 652 and the resistor 655, this arrangement being provided in order positively to insure that the go magnet 80X is fully energized promptly. When thus energized the control relay R650 operates to interrupt, at the contacts 652, the previously mentioned shunt around the winding thereof, whereby an obvious

holding circuit substantially identical to that previously traced is completed for energizing in series the winding of the control relay R650 and the go magnet 80X.

5 Also, the control relay R650 interrupts, at the contacts 651, the previously traced holding circuit for energizing in series the winding of the control relay R640 and the stop magnet 90X, thereby to cause the control relay R640 to restore and the stop magnet 90X to release. When the stop magnet 90X is thus released and the go magnet 80X is thus operated, the automatic switch incorporated in the selector 600 is clutched to the associated drive shaft, whereupon the first 10 motion thereof is initiated in the manner previously explained, whereupon the first motion normal switch 40X is operated. When the first motion normal switch 40X is thus operated there is completed, at the contacts 43 thereof, an 15 obvious alternative path for applying ground potential to the control conductor C663 of the trunk 660, thereby to retain both the trunk 660 and the calling subscriber line 601 marked as busy, as previously explained. Also, at the contacts 42 of the first motion normal switch 40X, there is completed a holding circuit for energizing in series the winding of the control relay R650 and the go magnet 80X, this circuit extending from ground by way of the contacts 613, the 20 contacts 72 of the second motion limit switch 70X, the contacts 42 of the first motion normal switch 40X, the contacts 653, the winding of R650 and the go magnet 80X to battery.

Also, upon restoring, the line relay R610 25 interrupts, at the contacts 612, the previously mentioned circuit for energizing the winding of the hold relay R620, thereby to cause the latter relay to restore shortly thereafter, the holding relay R620 being of the slow-to-release type. Upon 30 restoring, the hold relay R620 interrupts, at the contacts 622, a further point in the previously traced holding circuit for energizing in series the winding of the control relay R640 and the stop magnet 90X; interrupts, at the contacts 621, the 35 previously mentioned original path for applying ground potential to the control conductor C663 of the trunk 660, and interrupts, at the contacts 623, the previously traced original circuit for energizing in series the winding of the control relay R650 and the go magnet 80X.

Accordingly, at this time the wiper set 10X of the automatic switch incorporated in the selector 600 is being driven continuously in the first motion, in the manner previously explained; 40 and continues to be so driven until the conclusion of the first digit, whereupon the line relay R610 reoperates as previously explained. Upon reoperating, the line relay R610 interrupts, at the contacts 613, the previously traced holding circuit for energizing in series the winding of the control relay R650 and the go magnet 80X, thereby to cause the control relay R650 to restore and the go magnet 80X to release. Upon restoring, the control relay R650 completes, at the contacts 45 651, the previously traced original circuit for energizing in series the winding of the control relay R640 and the stop magnet 90X, thereby to cause both the control relay R640 and the stop magnet 90X to reoperate. Upon reoperating, the stop magnet 90X declutches the automatic switch incorporated in the selector 600 from the associated drive shaft, thereby positively to arrest further operation thereof in the first motion, in the manner previously explained. Also, upon reoperating, the line relay R610 recompletes, at the 50

contacts 612, the previously mentioned circuit for energizing the winding of the hold relay R620, thereby to cause the latter relay to reoperate in the event it restored during the first digit. Upon reoperating, the control relay R640 completes, at the contacts 643, a circuit for energizing the shift magnet 30X, this circuit extending from ground by way of the contacts 643, the contacts 41 of the first motion normal switch 40X, and the shift magnet 30X to battery. When thus energized, the shift magnet 30X operates to condition the automatic switch incorporated in the selector 600 to be operated in the second motion, in the manner previously explained, and completes, at the contacts 31, an alternative circuit for energizing in series the winding of the control relay R650 and the go magnet 80X, this circuit extending from ground by way of the contacts 31, the contacts 63 of the second motion normal switch 60X, the winding of R650 and the go magnet 80X to battery. When thus energized, the control relay R650 reoperates to interrupt, at the contacts 651, the previously traced holding circuit for energizing in series the winding of the control relay R640 and the stop magnet 90X, thereby to cause the control relay R640 to restore and the stop magnet 90X to release. At this time the automatic switch incorporated in the selector 600 is again clutched to the associated drive shaft, thereby to cause operation thereof in the second motion to be initiated in the manner previously explained. When the automatic switch incorporated in the selector 600 is operated in the second motion, the second motion normal switch 60X is operated thereby to complete, at the contacts 61 thereof, an obvious holding circuit including the set of switch springs 35X for energizing the shift magnet 30X, and to interrupt, at the contacts 63 thereof, the previously traced alternative circuit for energizing in series the winding of the control relay R650 and the go magnet 80X.

At this time a test circuit is completed between the test wiper 13 of the wiper set 10X and the winding of the control relay R650 and the go magnet 80X, this circuit extending from battery by way of the go magnet 80X, the winding of R650, the contacts 653, the contacts 42 of the first motion normal switch 40X, and the contacts 635 to the control wiper 13 of the wiper set 10X. At this time the go magnet 80X and the winding of the control relay R650 are energized in series circuit relation only in the event that ground potential appears upon the test wiper 13 of the wiper set 10X. Accordingly, the automatic switch incorporated in the selector 600 continues to operate in the second motion only so long as ground potential is retained upon the control wiper 13 of the wiper set 10X. In view of the fact that the control wiper 13 of the wiper set 10X is of the bridging type, ground potential is retained thereon only so long as the control wiper continues to test trunks extending to busy connectors, the trunk extending to a busy connector being marked by the presence of ground potential upon the control conductor thereof.

Assuming that the connector 700 is in the group previously selected by the selector 600, and that the connector 790 is the first idle connector in this group, when the control wiper 13 of the wiper set 10X tests the control conductor C793 of the trunk 790 extending to the connector 700, no ground potential appears thereon. Accordingly, the previously traced test circuit for energizing in series the winding of the control relay

R650 and the go magnet 80X is interrupted, thereby to cause the control relay R650 to restore and the go magnet 80X to release. Upon restoring, the control relay R650 interrupts, at the contacts 653, a further point in the previously traced test circuit extending to the control wiper 13 of the wiper set 10X and completes, at the contacts 651, the previously traced original circuit for energizing in series the winding of the control relay R640 and the stop magnet 90X, thereby to cause reoperation of the control relay R640 and the stop magnet 90X. When the go magnet 80X is thus released and the stop magnet 90X is thus operated, the automatic switch incorporated in the selector 600 is again declutched from the associated drive shaft, whereby the wiper set 10X has selected the trunk 790 extending to the connector 700.

Upon reoperating, the control relay R640 completes, at the contacts 642, a circuit for energizing the winding of the switch relay R630, this circuit extending from ground by way of the contacts 31 and 642, the winding of R630 and the contacts 73 of the second motion limit switch 70X to battery. When thus energized the switch relay R630 operates to complete, at the contacts 632 and 634, an obvious connection between the line conductors C661 and C662 of the trunk 660 and the line wipers 11 and 12 respectively of the wiper set 10X, whereby a loop circuit is completed between the calling subscriber substation T1 and the line relay R710 in the connector 700. This loop circuit extends from ground by way of the lower winding of R710, the line conductor C792 of the trunk 790, the line wiper 12 of the wiper set 10X, and the contacts 634 to the line conductor C662 of the trunk 660, and from the line conductor C661 of the trunk 660 by way of the contacts 632, the line wiper 11 of the wiper set 10X, the line conductor C791 of the trunk 790, and the upper winding of R710 to battery, a bridge connection being completed at the calling subscriber substation T1 by way of the line switch 602 between the line conductors C661 and C662 of the trunk 660.

When thus energized the line relay R710 in the connector 700 operates to complete, at the contacts 712, an obvious circuit for energizing the winding of the hold relay R720, thereby to cause the latter relay to operate. Upon operating, the hold relay R720 completes, at the contacts 721, an obvious path for applying ground potential to the control conductor C793 of the trunk 790 and, consequently, to the control wiper 13 of the wiper set 10X. This application of ground potential to the control wiper 13 of the wiper set 10X marks the connector 700 as busy to the other selectors having access thereto and completes an obvious holding circuit including the contacts 636 for energizing in series the winding of the control relay R640 and the stop magnet 90X in the selector 600.

Also, upon operating, the switch relay R630 interrupts, at the contacts 631 and 633, the previously traced loop circuit extending between the calling subscriber substation T1 and the upper and lower windings of the line relay R610 in the selector 600, thereby to cause the latter relay to restore. Upon restoring, the line relay R610 interrupts, at the contacts 612, the previously mentioned circuit for energizing the winding of the hold relay R620, thereby to cause the latter relay to restore shortly thereafter.

At this time an operative connection is completed between the calling subscriber substation

T1 and the connector 700 extending by way of the line switch 692, the trunk 669, the selector 690, and the trunk 700, and the connector 700 is in readiness to receive the second digit. In the selector 690 the shift magnet 36X and the stop magnet 99X are retained in their operated positions, thereby to retain operated the automatic switch incorporated therein. Also, in the selector 690 the switch relay R630 and the control relay R640 are retained in their operated positions thereafter, to prevent the release of the selector 690 in a manner more fully explained hereinafter. Also, when the line relay R710 in the connector 700 operates, it completes, at the contacts 711, a circuit for energizing in series the winding of the control relay R770 and the stop magnet 99Y, this circuit extending from ground by way of the contacts 711, the winding of R770 and the stop magnet 99Y to battery. It is noted that a shunt including the contacts 772 and the resistor 776 is normally completed about the winding of the control relay R770, this arrangement being provided in order positively to insure full energization of the stop magnet 99Y promptly. When thus energized the control relay R770 operates to interrupt, at the contacts 772, the previously mentioned shunt around the winding thereof, whereby an obvious holding circuit substantially identical to that previously traced is completed for energizing in series the winding of the control relay R770 and the stop magnet 99Y. When thus energized the stop magnet 99Y operates, thereby to insure that the automatic switch incorporated in the connector 700 is declutched from the associated drive shaft.

The subscriber at the calling subscriber substation T1 then proceeds to dial the second digit in the calling device 669, thereby to cause the previously traced loop circuit extending between the calling subscriber substation T1 and the line relay R710 in the connector 700 to be interrupted, to remain interrupted for a corresponding given time interval, and then to be recompleted at the expiration of the given time interval, whereby the line relay R710 in the connector 700 restores, remains restored for the given time interval and then reoperates at the expiration of the given time interval, in the manner previously explained. Upon restoring, the line relay R710 interrupts, at the contacts 711, the previously traced holding circuit for energizing in series the winding of the control relay R770 and the stop magnet 99Y, thereby to cause the control relay R770 to restore and the stop magnet 99Y to release. Also, upon restoring, the line relay R710 completes, at the contacts 713, a circuit for energizing in series the winding of the control relay R780 and the go magnet 80Y, this circuit extending from ground by way of the contacts 713 and 723, the contacts 62 of the second motion normal switch 60Y, the winding of R780 and the go magnet 80Y to battery. It is noted that a shunt including the contacts 781 and the resistor 784 is normally completed about the winding of the control relay R780, this arrangement being provided positively to insure full energization of the go magnet 80Y promptly. When thus energized the control relay R780 operates to interrupt, at the contacts 781, the previously mentioned shunt around the winding thereof, whereby a holding circuit substantially identical to that previously traced is completed for energizing in series the winding of the control relay R780 and the go magnet 80Y. When thus en-

ergized the go magnet 80Y operates, thereby to clutch the automatic switch incorporated in the connector 700 to the associated drive shaft, whereby operation of the automatic switch in the first motion is initiated in the manner previously explained.

When the automatic switch incorporated in the connector 700 is operated in the first motion, the first motion normal switch 48Y is operated, thereby to complete, at the contacts 43 thereof, an obvious alternative path for applying ground potential to the control conductor C193 of the trunk 700, thereby to retain the selector 690 in its operated position. Also, when the first motion normal switch 48Y is operated there is completed, at the contacts 42 thereof, a holding circuit for energizing in series the winding of the control relay R780 and the go magnet 80Y, this circuit extending from ground by way of the contacts 713, the contacts 71 of the second motion limit switch 79Y, the contacts 42 of the first motion normal switch 48Y, the contacts 783, the winding of R780 and the go magnet 80Y to battery.

The automatic switch incorporated in the connector 700 is operated continuously in the first motion in the manner previously explained, until the conclusion of the second digit, whereupon the line relay R710 reoperates as previously noted. Upon reoperating, the line relay R710 interrupts, at the contacts 713, the previously traced holding circuit for energizing in series the winding of the control relay R780 and the go magnet 80Y, thereby to cause the control relay R780 to restore and the go magnet 80Y to release. Also, the line relay R710 recomplicates, at the contacts 712, the previously mentioned circuit for energizing the winding of the hold relay R720, thereby to cause the hold relay R720 to reoperate in the event this relay has restored during the second digit, the hold relay R720 being of the slow-to-release type. Finally, the line relay R710 recompletes, at the contacts 711, the previously traced original circuit for energizing in series the winding of the control relay R770 and the stop magnet 99Y, thereby to cause reoperation of the control relay R770 and the stop magnet 99Y. When the go magnet 80Y is thus released and the stop magnet 99Y is thus operated the automatic switch incorporated in the connector 700 is declutched from the associated drive shaft. Accordingly, at this time the wiper set 10Y of the automatic switch incorporated in the connector 700 has been operated to select a group of subscriber lines including the subscriber line 781 extending to the called subscriber substation T2.

Upon reoperating, the control relay R770 completes, at the contacts 774, a circuit for energizing the shift magnet 36Y, this circuit extending from ground by way of the contacts 774, the contacts 41 of the first motion normal switch 40Y and the shift magnet 36Y to battery. When thus energized the shift magnet 36Y operates, thereby to condition the automatic switch incorporated in the connector 700 to be operated in the second motion, in the manner previously explained.

The subscriber at the calling subscriber substation T1 then proceeds to dial the third digit, whereby the line relay R710 in the connector 700 restores, remains restored during the time interval corresponding to the third digit dialed, and then reoperates in the manner previously explained. Upon restoring, the line relay R710

interrupts, at the contacts 711, the previously traced holding circuit for energizing in series the winding of the control relay R770 and the stop magnet 90Y, thereby to cause the control relay R770 to restore and the stop magnet 90Y to release. Also, the line relay R710 interrupts, at the contacts 712, the previously mentioned circuit for energizing the winding of the relay R720 and recompletes, at the contacts 713, the previously traced original circuit for energizing in series the winding of the control relay R780 and the go magnet 80Y, thereby to cause the control relay R780 and the go magnet 80Y to reoperate. Upon reoperating, the control relay R780 recompletes, at the contacts 783, the previously traced holding circuit for energizing in series the winding of the control relay R780 and the go magnet 80Y. When the stop magnet 90Y is thus released and the go magnet 80Y is thus operated, the automatic switch incorporated in the connector 700 is again clutched to the associated drive shaft, whereby operation thereof in the second motion is initiated in the manner previously explained. When the automatic switch incorporated in the connector 700 is operated in the second motion, the second motion normal switch 60Y is operated, thereby to complete, at the contacts 61 thereof, an obvious holding circuit including the set of switch springs 35Y for energizing the shift magnet 30Y. Also, when the second motion normal switch 60Y is operated there is interrupted, at the contacts 62 thereof, the previously mentioned original circuit for energizing in series the winding of the control relay R780 and the go magnet 80Y.

The automatic switch incorporated in the connector 700 is operated continuously in the second motion, in the manner previously explained, until the line relay R710 reoperates as previously noted. Upon reoperating, the line relay R710 recompletes, at the contacts 711, the previously traced original circuit for energizing in series the winding of the control relay R770 and the stop magnet 90Y, thereby to cause reoperation of the control relay R770 and the stop magnet 90Y. Also, the line relay R710 recompletes, at the contacts 712, the previously mentioned circuit for energizing the winding of the hold relay R720, thereby to cause reoperation of the hold relay R720 in the event this relay has restored during the third digit, in the manner previously explained. Finally, the line relay R710 interrupts, at the contacts 713, the previously traced holding circuit for energizing in series the winding of the control relay R780 and the go magnet 80Y, thereby to cause the control relay R780 to restore and the go magnet 80Y to release. When the go magnet 80Y is thus released and the stop magnet 90Y is thus operated, the automatic switch incorporated in the connector 700 is declutched from the associated drive shaft. Accordingly, at this time the wiper set 10Y in the automatic switch incorporated in the connector 700 has selected the subscriber line 701 extending to the called subscriber substation T2.

Upon reoperating, the control relay R770 completes, at the contacts 771, a test connection between the upper winding of the test relay R730 and the control wiper 13 of the wiper set 10Y, this test connection extending from battery by way of the upper winding of R730, the contacts 771 and 755 to the test wiper 13 of the wiper set 10Y. The subsequent operation of the connector 75

700 depends upon the idle or busy condition of the called subscriber substation T2, ground potential appearing upon the control conductor C701 of the subscriber line 701 in the event the called subscriber substation T2 is busy, and no potential appearing upon the control conductor C701 of the subscriber line 701 in the event the called subscriber substation T2 is idle.

Assuming that the called subscriber substation T2 is busy at this time, ground potential appears upon the control conductor C701 of the subscriber line 701 extending thereto, thereby to cause ground potential to be applied to the control wiper 13 of the wiper set 10Y. This application of ground potential to the control wiper 13 of the wiper set 10Y completes a path for short-circuiting the winding of the switch relay R750, this path extending from the grounded control wiper 13 of the wiper set 10Y by way of the contacts 755, the winding of R750, the contacts 773 and 722, and the contacts 63 of the second motion normal switch 60Y to ground. Also, this application of ground potential to the control wiper 13 of the wiper set 10Y completes a circuit for energizing the upper winding of the test relay R730, this circuit extending from the grounded control wiper 13 of the wiper set 10Y by way of the contacts 755 and 771 and the upper winding of R730 to battery. When thus energized the test relay R730 operates to complete, at the contacts 731, an obvious circuit including the busy tone conductor C727 and the condenser 728 for energizing the primary winding of the busy tone transformer 734, whereby busy tone current is projected over the line conductors C791 and C792 of the trunk 790. This circuit for projecting busy tone current over the line conductors C791 and C792 of the trunk 790 extends from ground by way of the lower winding of the line relay R710, the condenser 726, the contacts 754, the secondary winding of the busy tone transformer 734, the contacts 752, the condenser 724 and the upper winding of the line relay R710 to battery. The busy tone current projected over the line conductors C791 and C792 of the trunk 790 is extended by way of the selector 600, the trunk 660, the line switch 602 and the subscriber line 601 to the calling subscriber substation T1, thereby to indicate to the subscriber thereat that the desired connection may not immediately be had due to the busy condition of the called subscriber substation T2. The subscriber at the calling subscriber substation T1 then releases the line switch 602, the selector 600 and the connector 700 by replacing the receiver 604 of the telephone instrument thereat upon its associated switchhook, in a manner more fully explained hereinafter.

Assuming that the called subscriber substation T2 is idle at this time, no potential appears upon the control conductor C701 of the subscriber line 701 extending thereto. Accordingly, at this time the previously traced path for short-circuiting the winding of the switch relay R750, and the previously traced circuit for energizing the upper winding of the test relay R730, are not completed. However, at this time a circuit is completed for energizing in series the winding of the switch relay R750 and the upper winding of the test relay R730, this circuit extending from ground by way of the contacts 63 of the second motion normal switch 60Y, the contacts 722 and 773, the winding of R750, the contacts 771 and the upper winding of R730 to battery. When this series circuit is completed the switch relay R750

operates; however, the test relay R730 does not operate due to the high series resistance of the winding of the switch relay R750, the test relay R730 being of the marginal type. Upon operating, the switch relay R750 completes, at the contacts 756, an obvious path for applying ground potential to the control wiper 13 of the wiper set 10Y and, consequently, to the control conductor C701 of the subscriber line 701 extending to the called subscriber substation T2. This application of ground potential to the control conductor C701 of the subscriber line 701 marks the called subscriber substation T2 as busy to the other connectors having access thereto. Also, the switch relay R750 interrupts, at the contacts 752 and 754, the normal connection between the secondary winding of the busy tone transformer 734 and the line conductors C791 and C792 of the trunk 790, and completes, at the contacts 751 and 753, an obvious connection including the condensers 724 and 726 between the line conductors C791 and C792 of the trunk 790, and the line wipers 11 and 12 of the wiper set 10Y. Further the switch relay R750 completes, at the contacts 757 and 758, a connection between the upper and lower windings of the answer relay R740 and the line wipers 11 and 12 of the wiper set 10Y, for a purpose more fully explained hereinafter.

Finally, the switch relay R750 completes, at the contacts 759, an obvious circuit including the interrupter conductor C724 for energizing the winding of the ring relay R760, whereby the winding of the ring relay R760 is energized intermittently, thereby to cause the ring relay R760 to operate and restore intermittently. Each time the ring relay R760 operates it completes, at the contacts 762 and 764, a circuit for projecting ringing current over the subscriber line 701, this circuit extending from ground by way of the contacts 764 and the line wiper 12 of the wiper set 10Y to one of the line conductors of the subscriber line 701, and from the ringing conductor C765 by way of the contacts 762 and the line wiper 11 of the wiper set 10Y to the other line conductor of the subscriber line 701, the ringing conductor C765 being connected by way of the winding of a ringing transformer, not shown, to ground; and a ringer, not shown, at the called subscriber substation T2 being bridged across the line conductors of the subscriber line 701. Each time the ring relay R760 restores it interrupts, at the contacts 762 and 764, the previously traced circuit for projecting ringing current over the subscriber line 701 to the called subscriber substation T2, and prepares, at the contacts 761 and 763, a circuit traced hereinafter for energizing in series the upper and lower windings of the answer relay R740. Accordingly, at this time the ringer at the called subscriber substation T2 is operated, thereby to indicate to the subscriber thereat that the subscriber substation T2 is being called.

When the subscriber at the called subscriber substation T2 answers the call by removing the receiver 704 of the telephone instrument thereat from its associated switchhook, the hook switch 705 is operated thereby to complete a bridge connection including the transmitter 703, the calling device 706, and the receiver 704 between the line conductors of the subscriber line 701. Upon the next restoration of the ring relay R760, the previously mentioned circuit for energizing in series the upper and lower windings of the answer relay R740 is completed at the contacts 761 and 763. This circuit extends from ground by way

of the lower winding of R740, the contacts 758 and 763 and the line wiper 12 of the wiper set 10Y to one of the line conductors of the subscriber line 701, and from battery by way of the upper winding of R740, the contacts 757 and 761 and the line wiper 11 of the wiper set 10Y to the other line conductor of the subscriber line 701, the line conductors of the subscriber line 701 being bridged at the called subscriber substation T2, as previously noted. When thus energized the answer relay R740 operates to complete, at the contacts 741, an obvious circuit for energizing the lower winding of the test relay R730. When thus energized the test relay R730 operates, whereby the test relay R730 is retained in its operated position, the upper winding of the test relay R730 being energized in series with the winding of the switch relay R750 by way of the previously traced circuit. At this point it is noted that while the test relay R730 will not operate when the upper winding thereof is energized in series with the winding of the switch relay R750, it will remain in its operated position when the upper winding thereof is so energized, the test relay R730 being of the marginal type as previously explained. Upon operating, the test relay R730 interrupts, at the contacts 732, the previously mentioned circuit for energizing the lower winding thereof and interrupts, at the contacts 733, the previously traced circuit for energizing the winding of the ring relay R760, thereby to cause the ring relay R760 to remain restored.

At this time the connector 700 is fully operated, the line relay R710, the hold relay R720, the test relay R730, the answer relay R740, the switch relay R750 and the control relay R770 remaining in their operated positions. Also, the shift magnet 30Y and the stop magnet 90Y are retained in their operated positions, thereby to retain the automatic switch incorporated in the connector 700 in its operated position. At this time a communication connection is established between the calling subscriber substation T1 and the called subscriber substation T2. More particularly, the previously traced loop circuit between the calling subscriber substation T1 and the line relay R710 in the connector 700 is completed, and the previously traced loop circuit between the called subscriber substation T2 and the answer relay R740 in the connector 700 is completed; while the line relay R710 and the answer relay R740 are operatively connected by way of the contacts 751 and 753 and the condensers 724 and 726, as previously explained. Accordingly, the telephone instrument at the calling subscriber substation T1 and the telephone instrument at the called subscriber substation T2 are operatively connected for two-way communication therebetween by way of the established connection including the subscriber line 601, the line switch 602, the trunk 660, the selector 600, the trunk 790, the connector 700 and the subscriber line 701.

The release of this established connection is under the control of the subscriber at the calling subscriber substation T1 and is effected when the subscriber thereat replaces the receiver 604 of the telephone instrument at the calling subscriber substation T1 upon its associated switchhook, whereupon the hook switch 605 is operated, thereby to interrupt the previously traced loop circuit for energizing in series the upper and lower windings of the line relay R710 in the connector 700. When the loop circuit extending between the calling subscriber substation T1 and the line relay

R710 is thus interrupted, the line relay R710 restores thereby to interrupt, at the contacts 711, the previously traced holding circuit for energizing in series the winding of the control relay R770 and the stop magnet 90Y, whereupon the control relay R770 restores and the stop magnet 90Y is released. Also, the line relay R710 interrupts, at the contacts 712, the previously mentioned circuit for energizing the winding of the hold relay R720, thereby to cause the latter relay to restore shortly thereafter, as previously explained. Upon restoring, the control relay R770 interrupts, at the contacts 711 and 713, the previously traced series holding circuit for energizing in series the winding of the switch relay R750 and the upper winding of the test relay R730, thereby to cause the test relay R730 to restore immediately and to cause the switch relay R750 to restore shortly thereafter, the switch relay R750 being of the slow-to-release type. Upon restoring, the switch relay R750 interrupts, at the contacts 757 and 758, the previously traced loop circuit extending between the called subscriber substation T2 and the answer relay R740 in the connector 700, thereby to cause the latter relay to restore.

When the stop magnet 90Y is released, the automatic switch incorporated in the connector 700 is released, this automatic switch being first returned to its normal position in the second motion and then returned to its normal position in the first motion, in the manner previously explained, whereby the second motion normal switch 60Y and then the first motion normal switch 40Y are successively operated. When the second motion normal switch 60Y is operated there is interrupted, at the contacts 61 thereof, the previously traced holding circuit for energizing the shift magnet 30Y, thereby to cause the shift magnet 30Y to release shortly thereafter, the latter magnet being of the slow-to-release type. When the first motion normal switch 40Y is operated there is interrupted, at the contacts 43 thereof, the previously mentioned path for applying ground potential to the control conductor C793 of the trunk 790. At this time the connector 700 is completely released and is marked as idle to the selectors having access thereto by the absence of potential upon the control conductor C793 of the trunk 790 extending thereto.

When the connector 700 is thus released and rendered available for further use, ground potential is removed from the control conductor C701 of the subscriber line 701, thereby to cause the line switch 702 to operate in order to lock the subscriber substation T2 out of service in the event the subscriber thereat has not replaced the receiver 704 of the telephone instrument at the subscriber substation T2 upon its associated switchhook at this time, in accordance with conventional practice. On the other hand, in the event the subscriber at the subscriber substation T2 has replaced the receiver 704 thereat upon its associated switchhook at this time, the line switch 702 is completely released and the subscriber substation T2 is marked as idle to the connections having access thereto by the absence of potential upon the control conductor C701 of the subscriber line 701 extending thereto.

When the connector 700 is thus released ground potential is removed from the control conductor C793 of the trunk 790, as previously mentioned, thereby to interrupt the previously traced holding circuit for energizing in series the winding of the control relay R640 and the stop magnet 90X in

the selector 600, whereupon the control relay R640 restores and the stop magnet 90X is released. Upon restoring, the control relay R640 interrupts, at the contacts 642, the previously traced circuit for energizing the winding of the switch relay R630, thereby to cause the latter relay to restore.

When the stop magnet 90X is thus released the automatic switch incorporated in the selector 600 is automatically released, this switch being returned to its normal position in the second motion and then returned to its normal position in the first motion, in the manner previously explained. When the automatic switch incorporated in the selector 600 is thus released, the second motion normal switch 60X and then the first motion normal switch 40X are successively operated, in the manner previously explained. When the second motion normal switch 60X is thus operated there is interrupted, at the contacts 61 thereof, the previously traced holding circuit for energizing the shift magnet 30X, thereby to cause the shift magnet 30X to release shortly thereafter, the latter magnet being of the slow-to-release type. When the first motion normal switch 40X is thus operated there is interrupted, at the contacts 43 thereof, the previously mentioned path for applying ground potential to the control conductor C663 of the trunk 660. Accordingly, at this time the selector 600 is completely released and rendered available for further use, the selector 600 being marked as idle to the line switches having access thereto by the absence of potential upon the control conductor C663 of the trunk 660 extending thereto.

When the selector 600 is thus released ground potential is removed from the control conductor C663 of the trunk 660 as previously noted, whereupon the line switch 602 is released, thereby to remove the application of ground potential to the control conductor C601 of the subscriber line 601. When the ground potential is removed from the control conductor C601 of the line 601 the subscriber substation T1 is marked as idle to the connectors having access thereto. At this time the apparatus utilized in establishing the connection between the calling subscriber substation T1 and the called subscriber substation T2 is completely released and rendered available for further use.

In connection with the release of the connector 700 it is pointed out that the release thereof is precisely as described above in the event that the automatic switch incorporated therein is of the character of the automatic switch 100; however, the exact mode of release of the connector 700 departs slightly from that described above in the event the automatic switch incorporated therein is of the character of the automatic switch 400. This slight departure in the mode of release of the connector 700 resides in the operation of the release magnet 85Y of the automatic switch 400. More particularly, in the event the automatic switch 400 is incorporated in the connector 700, when the release of the connector 700 is initiated, the control relay R770 restores as previously explained. Also, in this event the control relay R770 completes, at the contacts 775, a circuit for energizing the release magnet 85Y, this circuit extending from ground by way of the contacts 782, 755 and 31, and the release magnet 85Y to battery. Shortly after the release magnet 85 is thus energized, this magnet being of the slow-to-operate type, the release magnet 85Y operates to release the automatic switch 400 in-

corporated in the connector 700, in the manner previously explained, and to complete at the set of switch springs 95Y a holding circuit for energizing the release magnet 85Y. The holding circuit for energizing the release magnet 85Y extends from ground by way of the contacts 44 of the first motion normal switch 40Y, the set of switch springs 95Y and the release magnet 85Y to battery. The release of the connector 700 proceeds in the manner previously explained and when the automatic switch 400 incorporated therein is returned to its normal position in the first motion, the first motion normal switch 40Y is operated thereby to interrupt, at the contacts 44 thereof, the previously traced holding circuit for energizing the release magnet 85Y, whereupon the release magnet 85Y is released.

In connection with the release of the selector 600 it is pointed out that the release thereof is precisely as described above in the event that the automatic switch incorporated therein is of the character of the automatic switch 100; however, the exact mode of release of the selector 600 departs slightly from that described above in the event the automatic switch incorporated therein is of the character of the automatic switch 400. This slight departure in the mode of release of the selector 600 resides in the operation of the release magnet 85X of the automatic switch 400. More particularly, in the event the automatic switch 400 is incorporated in the selector 600, when the release of the selector 600 is initiated, the control relay R640 restores as previously explained. Also, in this event the control relay R640 completes, at the contacts 644, a circuit for energizing the release magnet 85X, this circuit extending from ground by way of the contacts 654, 644 and 32 and the winding of the release magnet 85X to battery. Shortly after the release magnet 85X is thus energized, this magnet being of the slow-to-operate type, the release magnet 85X operates to release the automatic switch 400 incorporated in the selector 600, in the manner previously explained, and to complete at the set of switch springs 95X a holding circuit for energizing the release magnet 85X. The holding circuit for energizing the release magnet 85X extends from ground by way of the contacts 44 of the first motion normal switch 40X, the set of switch springs 95X and the release magnet 85X to battery. The release of the selector 600 proceeds in the manner previously explained and when the automatic switch 400 incorporated therein is returned to its normal position in the first motion, the first motion normal switch 40X is operated thereby to interrupt, at the contacts 44 thereof, the previously traced holding circuit for energizing the release magnet 85X, whereupon the release magnet 85X is released.

In the foregoing explanation of the mode of operation of the selector 600 it was assumed that after the line switch 602 seized the trunk 660 extending thereto, the subscriber at the calling subscriber substation T1 dialed a proper first digit thereinto; however, it may occur that the subscriber at the calling subscriber substation T1 replaces the receiver 604 of the telephone instrument thereat upon its associated switchhook after initiating the call and before dialing any digit. When the call at the calling subscriber substation T1 is thus abandoned prior to the time the subscriber at the calling subscriber substation T1 dials the first digit the line relay R610 in the selector 600 restores and remains restored

for an indefinite time interval. When the selector 600 is thus seized by the line switch 602 operation thereof is initiated in the manner previously explained. However, in this event a first digit 11 is in effect dialed thereinto, in view of the fact that the line relay R610 remains restored for an indefinite time interval. In this event the automatic switch incorporated in the selector 600 is continuously operated in the first motion to the extreme limit thereof, whereupon the first motion limit switch 50X is operated, thereby to complete at the contacts 51 thereof an alternative circuit for energizing the shift magnet 30X, this circuit extending from ground by way of the contacts 51 of the first motion limit switch 50X, the contacts 41 of the first motion normal switch 40X, and the shift magnet 30X to battery. When thus energized the shift magnet 30X operates, thereby to cause the automatic switch incorporated in the selector 600 to be operated in the second motion, in the manner previously explained. At this time a holding circuit for energizing in series the go magnet 80X and the winding of the control relay R650 is continuously completed, this circuit extending from ground by way of the contacts 613, the contacts 72 of the second motion limit switch 70X, the contacts 42 of the first motion normal switch 40X, the contacts 653, the winding of R650 and the go magnet 80X to battery.

Accordingly, at this time the automatic switch incorporated in the selector 600 is operated in the second motion continuously to the ultimate limit thereof, whereupon the second motion limit switch 70X is operated, thereby to interrupt at the contacts 72 thereof the above traced holding circuit for energizing in series the winding of the control relay R650 and the go magnet 80X, thereby to cause the control relay R650 to restore and the go magnet 80X to release. Upon restoring, the control relay R650 interrupts, at the contacts 653, a further point in the above traced holding circuit for energizing in series the upper winding of the control relay R650 and the go magnet 80X. Hence, when the go magnet 80X is released the automatic switch incorporated in the selector 600 is released, in the manner previously explained, in view of the fact that the stop magnet 90X is not operated at this time. When the selector 600 is released the automatic switch incorporated therein is first returned to its normal position in the second motion and then returned to its normal position in the first motion, whereupon the second motion limit switch 70X, the second motion normal switch 60X, the first motion limit switch 50X and the first motion normal switch 40X are operated sequentially, in the manner previously explained. Accordingly, at this time the selector 600 is completely released and rendered available for further use.

Also, in the foregoing explanation of the mode of operation of the selector 600 it was assumed that at the conclusion of the first digit dialed thereinto, the selector 600 operated to find a trunk extending to an idle connector, such as the connector 700; however, it may occur that all of the connectors in the previously selected group are busy at this time. In this event the automatic switch incorporated in the selector 600 is operated continuously in the second motion to the ultimate limit thereof, whereupon the second motion limit switch 70X is operated, in the manner previously explained. When the control wiper 13 of the wiper set 19X of the automatic switch incorporated in the selector switch 400 engages

the eleventh contact set in the previously selected group or row of contact sets, ground potential is removed therefrom, as the eleventh contact set in the previously selected row of contact sets does not terminate a trunk, whereupon the previously traced holding circuit for energizing in series the winding of the control relay R650 and the go magnet 80X is interrupted, thereby to cause the control relay R650 to restore and the go magnet 80X to release. Upon restoring, the control relay R650 recompletes, at the contacts 631, the previously traced original circuit for energizing in series the winding of the control relay R640 and the stop magnet 90X, thereby to cause operation of the control relay R640 and the stop magnet 90X, in the manner previously explained.

In this event, when the second motion limit switch 70X is operated there is interrupted, at the contacts 73 thereof, a point in the previously traced circuit for energizing the winding of the switch relay R630, thereby to prevent operation of the latter relay at this time. Also, at the contacts 72 of the second motion limit switch 70X, there is interrupted a further point in the previously traced alternative holding circuit for energizing in series the winding of the control relay R650 and the go magnet 80X. Finally, at the contacts 71 of the second motion limit switch 70X, there is completed a circuit for returning busy tone current over the trunk 660, this circuit extending from the ungrounded terminal of a grounded winding of a busy tone transformer, not shown, by way of the busy conductor C616, the condenser 617, and the contacts 71 of the second motion limit switch 70X, to the line conductor C662 of the trunk 660, and from battery by way of the upper winding of the line relay R610 and the contacts 631 to the line conductor C661 of the trunk 660, the line conductors C661 and 40 C662 of the trunk 660 being connected by way of the line switch 602 and the subscriber line 601 to the calling subscriber substation T1. The busy tone current projected over the above-traced circuit to the calling subscriber substation T1 causes the receiver 604 of the telephone instrument thereat to operate in order to produce busy tone, thereby to indicate to the subscriber at the calling subscriber substation T1 that the desired connection may not immediately be had due to the 50 all-trunks-busy condition at the present time. The subscriber at the calling subscriber substation T1 then proceeds to release the connection by replacing the receiver 604 of the telephone instrument thereat upon its associated switchhook, thereby to effect the release of the selector 600 in the manner previously described.

In the foregoing explanation of the mode of operation of the connector 700 it was assumed that, after the selector 600 seized the trunk 790 extending thereto, the subscriber at the calling subscriber substation T1 dialed a proper second digit thereto; however, it may occur that the subscriber at the calling subscriber station T1 replaces the receiver 604 of the telephone instrument thereat upon its associated switchhook after dialing the first digit, thereby to cause in effect a second digit 11 to be transmitted to the connector 700. Similarly, the subscriber at the calling subscriber substation T1, after the selector 600 has seized the trunk 790 extending to the connector 700, may dial a proper second digit into the connector 700 and then replace the receiver 604 of the telephone instrument thereat upon its associated switchhook, thereby in effect to cause

70 a third digit 11 to be transmitted to the connector 700.

In the event a second digit 11 is transmitted to the connector 700, the automatic switch incorporated therein is operated in the first motion to the ultimate limit thereof, thereby to cause operation of the first motion limit switch 50Y. When the first motion limit switch 50Y is thus operated there is completed, at the contacts 51 thereof, an alternative circuit for energizing the shift magnet 30Y, this circuit extending from ground by way of the contacts 51 of the first motion limit switch 50Y, the contacts 41 of the first motion normal switch 40Y and the shift magnet 30Y to battery. When thus energized the shift magnet 30Y operates, thereby to cause the automatic switch incorporated in the connector 700 to be operated in the second motion in the manner previously explained. At this time the automatic switch incorporated in the connector 700 is continuously operated in the second motion to the ultimate limit thereof, whereupon the second motion limit switch 70Y is operated, thereby to interrupt, at the contacts 71 thereof, the previously traced alternative circuit for energizing in series the winding of the control relay R780 and the go magnet 80Y, whereupon the control relay R780 restores and the go magnet 80Y releases. When the go magnet 80Y is thus released the automatic switch incorporated in the connector 700 is automatically released in the manner previously explained, in view of the fact that the line relay R710 occupies its restored position at this time. When the automatic switch incorporated in the connector 700 is thus released the second motion limit switch 70Y, the second motion normal switch 60Y, the first motion limit switch 50Y, and the first motion normal switch 40Y are sequentially operated in the manner previously explained.

Similarly, in the event a third digit 11 is transmitted to the connector 700 the automatic switch incorporated therein is operated continuously in the second motion to the ultimate limit thereof, whereupon the second motion limit switch 70Y is operated, thereby to effect the release of the connector 700 in the manner previously explained.

In view of the foregoing explanation of the mode of operation of the connector 700, it will be understood that it is automatically released incident to false dialing thereinto, in the event the subscriber at the calling subscriber substation T1 abandons the call prior to complete operation of the connector 700.

Further, it will be understood that when the connector 700 is automatically released, the selector 600 and the line switch 602 are automatically released in the manner previously explained.

60 While there has been described what is at present considered to be the preferred embodiment of the automatic switch from a mechanical standpoint, and the preferred embodiment of each of the automatic switches from an electrical standpoint, as well as the system, it will be understood that various modifications may be made therein and it is contemplated to cover in the appended claims all such modifications as fall within the true spirit and scope of the invention.

70 75 What is claimed is:

1. An automatic switch comprising a contact controlling member mounted for both primary and secondary movements, an element operatively connected to said member and supported for both rotary and sliding movements, whereby primary

movement is imparted to said member when said element is rotated and secondary movement is imparted to said member when said element is slid, a shaft operatively connected to said element and supported for rotary movement, whereby said element tends both to rotate and to slide when said shaft is rotated, locking mechanism selectively operative first to lock said element against sliding and then to lock said element against rotation, thereby selectively to control both primary and secondary movements of said member, and means operative repeatedly for imparting selective continuous rotation to said shaft, thereby selectively to control the amount of primary movement of said member and then selectively to control the amount of secondary movement of said member.

2. An automatic switch comprising a contact controlling member mounted for both primary and secondary movements, an element operatively connected to said member and supported for both rotary and sliding movements, whereby primary movement is imparted to said member when said element is rotated and secondary movement is imparted to said member when said element is slid, a shaft operatively connected to said element and supported for rotary movement, whereby said element tends both to rotate and to slide when said shaft is rotated, locking mechanism operative selectively to lock said element against rotation and against sliding, thereby selectively to control both primary and secondary movements of said member, said element and said shaft being so constructed and arranged that said member is operated when said shaft is rotated in a given direction and that said member is released when said shaft is rotated in a reverse direction, means operative repeatedly for imparting selective continuous rotation to said shaft in said given direction, thereby selectively to control the amount of primary operating movement of said member and then selectively to control the amount of secondary operating movement of said member, and means including a spring motor operatively connected to said shaft for imparting continuous rotation to said shaft in said reverse direction, thereby to control both the secondary releasing movement of said member and the primary releasing movement of said member.

3. An automatic switch comprising a contact controlling member mounted for both primary and secondary movements, an element operatively connected to said member and supported for both rotary and sliding movements, whereby primary movement is imparted to said member when said element is rotated and secondary movement is imparted to said member when said element is slid, a shaft supported for rotary movement, a cylindrical spiral drive connection between said shaft and said element, whereby said element tends both to rotate and to slide when said shaft is rotated, locking mechanism selectively operative first to lock said element against sliding and then to lock said element against rotation, thereby selectively to control both primary and secondary movements of said member, and means operative repeatedly for imparting selective continuous rotation to said shaft, thereby selectively to control the amount of primary movement of said member and then selectively to control the amount of secondary movement of said member.

4. An automatic switch comprising a contact controlling member mounted for both lateral and longitudinal movements, an element supported

for both rotary and sliding movements, a first drive connection between said element and said member, whereby said member is moved laterally when said element is rotated, a second drive connection between said element and said member, whereby said member is moved longitudinally when said element is slid, a shaft operatively connected to said element and supported for rotary movement, whereby said element tends both to rotate and to slide when said shaft is rotated, locking mechanism selectively operative first to lock said element against sliding and then to lock said element against rotation, thereby selectively to control both lateral and longitudinal movements of said member, and means operative repeatedly for imparting selective continuous rotation to said shaft, thereby selectively to control the amount of lateral movement of said member and then selectively to control the amount of longitudinal movement of said member.

5. An automatic switch comprising a contact controlling member mounted for both lateral and longitudinal sliding movements, an element supported for both rotary and sliding movements, a first drive connection between said element and said member, whereby said member is slid laterally when said element is rotated, a second drive connection between said element and said member, whereby said member is slid longitudinally when said element is slid, a shaft supported for rotary movement, a cylindrical spiral drive connection between said shaft and said element, whereby said element tends both to rotate and to slide when said shaft is rotated, locking mechanism selectively operative first to lock said element against sliding and then to lock said element against rotation, thereby selectively to control both lateral and longitudinal sliding movements of said member, and means operative repeatedly for imparting selective continuous rotation to said shaft, thereby selectively to control the amount of lateral sliding movement of said member and then selectively to control the amount of longitudinal sliding movement of said member.

6. An automatic switch comprising a flat, rectangular contact bank including a plurality of laterally spaced-apart rows of longitudinally extending contact sets, a contact controlling member operatively associated with said contact bank and mounted for both lateral and longitudinal movements, an element operatively connected to said member and supported for both rotary and sliding movements, whereby said member is moved laterally progressively to select said rows of contact sets when said element is rotated and moved longitudinally progressively to select the contact sets in a selected one of said rows of contact sets when said element is slid, a shaft operatively connected to said element and supported for rotary movement, whereby said element tends both to rotate and to slide when said shaft is rotated, locking mechanism selectively operative first to lock said element against sliding and then to lock said element against rotation; thereby selectively to control both lateral and longitudinal movements of said member, and means operative repeatedly for imparting selective continuous rotation to said shaft, thereby selectively to control the amount of lateral movement of said member and then selectively to control the amount of longitudinal movement of said member.

7. An automatic switch comprising a longitudinally extending shaft supported for rotation,

an element supported for both rotary and longitudinal movements, a contact controlling member carried by said element, a drive connection between said shaft and said element, whereby said element tends both to rotate and to move longitudinally when said shaft is rotated, locking mechanism selectively operative first to lock said element against longitudinal movement and then to lock said element against rotary movement, thereby selectively to control both rotary and longitudinal movements of said member, and means operative repeatedly for imparting selective continuous rotation to said shaft, thereby selectively to control the amount of rotary movement of said member and then selectively to control the amount of longitudinal movement of said member.

8. An automatic switch comprising a longitudinally extending shaft supported for rotation, an element carried by said shaft and supported for rotary movement with said shaft and longitudinal sliding movement along said shaft, a contact controlling member carried by said element, a cylindrical spiral drive connection between said shaft and said element, whereby said element tends both to rotate and to slide longitudinally when said shaft is rotated, locking mechanism selectively operative first to lock said element against longitudinal sliding and then to lock said element against rotation, thereby selectively to control both rotary and longitudinal movements of said member, and means operative repeatedly for imparting selective continuous rotation to said shaft, thereby selectively to control the

amount of rotary movement of said member and then selectively to control the amount of longitudinal movement of said member.

9. An automatic switch comprising a semi-cylindrical contact bank including a plurality of circumferentially spaced-apart rows of longitudinally extending contact sets, a longitudinally extending shaft supported for rotation, an element carried by said shaft and supported for rotary movement with said shaft and longitudinal sliding movement along said shaft, a contact controlling member carried by said element and operatively associated with said contact bank, whereby said member is rotated progressively to 10 select said rows of contact sets when said element is rotated and moved longitudinally progressively to 15 select the contact sets in a selected one of said rows of contact sets when said element is slid longitudinally, a drive connection between said shaft and said element, whereby said element tends both to rotate and to slide longitudinally when said shaft is rotated, locking mechanism selectively operative first to lock said element against longitudinal sliding and then to lock said element against rotation, thereby selectively to 20 control both rotary and longitudinal movements of said member, and means operative repeatedly for imparting selective continuous rotation to said shaft, thereby selectively to control the amount 25 of rotary movement of said member and then selectively to control the amount of longitudinal movement of said member.

BERNARD D. WILLIS.
